(57) **ABSTRACT**

A dishwasher including a tub; a door to open and close the tub; an input device to receive a selection of a washing course; and an automatic detergent dispenser including a storage compartment in which a plurality of solid detergents are stackable, an ejector to discharge a solid detergent outside of the storage compartment, a seating member on which a solid detergent discharged from the storage compartment is seatable, a detector to detect whether a solid detergent is seated on the seating member, and a processor configured to control the ejector to operate so that, when a plurality of solid detergents are loaded in the storage compartment, one solid detergent among the plurality of solid detergents is discharged outside of the storage compartment to be seated on the seating member, and determine whether

(Continued)

a solid detergent is seated on the seating member based on a detection result of the detector.

CROSS-REFERENCE TO RELATED APPLICATION(S)

This application is a continuation application, under 35 U.S.C. § 111(a), of international application No. PCT/KR2023/011722, filed on Aug. 9, 2023, which claims priority to Korean Patent Application No. 10-2022-0146530, filed on Nov. 4, 2022, in the Korean Intellectual Property Office, the disclosures of which are incorporated by reference herein in their entireties.

BACKGROUND

1. Field

The disclosure relates to a dishwasher and a control method thereof and more particularly, to a dishwasher including a device configured to input detergent, and a control method thereof.

2. Description of Related Art

A dishwasher is a device that automatically removes food residues and the like on dishes using detergent and wash water.

The dishwasher includes a main body, a washing chamber formed by a tub disposed inside the main body, a storage container disposed inside the washing chamber to store dishes, and a spray unit configured to spray wash water to the storage container.

The storage container may be usually provided in two or three stages, and the spray unit may be provided in plurality and disposed to correspond to the storage container so as to spray wash water to each place, in which each storage container is disposed.

The dishwasher may include a drain hose to drain wash water to the outside after the wash water is sprayed inside the washing chamber and washes dishes.

In order to prevent the reverse flow in the drain hose, at least a portion of the drain hose may be arranged to have a curved shape at a position higher than the lower surface of the washing chamber.

A conventional dishwasher may include the above-described shape, and at least three or more additional components to fix the above-described shape to the inside of the dishwasher.

In addition, an automatic detergent dispenser of the conventional dishwasher may store detergent for one-time use or for multiple-times use. However, an amount of detergent that can be stored once is small, and thus a user has to periodically re-store the detergent.

SUMMARY

Aspects of embodiments of the disclosure will be set forth in part in the description which follows and, in part, will be apparent from the description, or may be learned by practice of the presented embodiments.

According to an embodiment of the disclosure, a dishwasher includes a tub; a door to open and close the tub; an input device to receive a selection of a washing course; and an automatic detergent dispenser including a storage compartment in which a plurality of solid detergents are stackable so as to be loaded in a vertical direction when the tub

is closed by the door, an ejector to discharge a solid detergent, among the plurality of solid detergents loaded in the storage compartment, outside of the storage compartment, a seating member on which a solid detergent discharged from the storage compartment is seatable, a detector to detect whether a solid detergent is seated on the seating member, and a processor configured to, in response to a selection of a washing course being received through the input device, control the ejector to operate so that, when a plurality of solid detergents are loaded in the storage compartment, one solid detergent among the plurality of solid detergents is discharged outside of the storage compartment to be seated on the seating member, and determine whether a solid detergent is seated on the seating member based on a detection result of the detector.

According to an embodiment of the disclosure, the ejector may include a cam member configured to rotate in a forward direction to discharge the one solid detergent outside of the storage compartment, and the processor may be configured to rotate the cam member one time in the forward direction to discharge the one solid detergent outside of the storage compartment.

According to an embodiment of the disclosure, the detector may include a seating member sensor to detect an object seated on the seating member, and the processor may be configured to determine whether a solid detergent is seated on the seating member based on an output of the seating member sensor.

According to an embodiment of the disclosure, the processor may be configured to rotate the cam member a second time in the forward direction in response to determining that a solid detergent is not seated on the seating member.

According to an embodiment of the disclosure, the processor may be configured to, in response to determining that a solid detergent is not seated on the seating member after rotating the cam member the second time in the forward direction, generate a control signal to provide a notification that a solid detergent is not present in the storage compartment.

According to an embodiment of the disclosure, the automatic detergent dispenser may include a seating member door to open to input a solid detergent seated on the seating member into the tub, and the processor may be configured to open the seating member door to input the solid detergent seated on the seating member into the tub at a stage of supplying water for a main washing operation.

According to an embodiment of the disclosure, the detector may include a storage compartment sensor to detect a solid detergent inside of the storage compartment, and the processor may be configured to determine whether a solid detergent is present in the storage compartment based on an output of the storage compartment sensor.

According to an embodiment of the disclosure, the processor may be configured to determine whether an error in discharging the one solid detergent occurred based on the detection result of the detector, and rotate the cam member in a reverse direction in response to determining that the error occurred.

According to an embodiment of the disclosure, the processor may be configured to determine whether an error in discharging the one solid detergent occurred based on power consumption or rotational speed of a motor inside the ejector.

According to an embodiment of the disclosure, the storage compartment may include a first storage compartment, and a second storage compartment spaced apart from the first storage compartment in a left and right direction that is

perpendicular to the vertical direction, and the ejector may include a first ejector to discharge a solid detergent, among a plurality of solid detergents loaded in the first storage compartment, to the seating member, and a second ejector to discharge a solid detergent, among a plurality of solid detergents loaded in the second storage compartment, to the seating member.

According to an embodiment of the disclosure, the first ejector may include a first cam member configured to rotate in a forward direction to discharge the one solid detergent outside of the first storage compartment, and the second ejector may include a second cam member configured to rotate in the forward direction to move the one solid detergent outside of the second storage compartment.

According to an embodiment of the disclosure, the processor may be configured to rotate the first cam member one time in the forward direction to discharge the one solid detergent outside of the first storage compartment.

According to an embodiment of the disclosure, the processor may be configured to rotate the first cam member a second time in the forward direction in response to determining that a solid detergent is not seated on the seating member after rotating the first cam member.

According to an embodiment of the disclosure, the processor may be configured to, in response to determining that a solid detergent is not seated on the seating member after rotating the first cam member the second time in the forward direction, rotate the second cam member one time in the forward direction to discharge the one solid detergent outside of the second storage compartment.

According to an embodiment of the disclosure, the processor may be configured to, in response to determining that a solid detergent is not seated on the seating member after rotating the second cam member, rotate the second cam member a second time in the forward direction.

According to an embodiment of the disclosure, the processor may be configured to, in response to determining that a solid detergent is not seated on the seating member after rotating the second cam member the second time in the forward direction, generate a control signal to provide a notification that a solid detergent is not present in the storage compartment.

According to an embodiment of the disclosure, the processor may be configured to, in response to determining that a solid detergent is seated on the seating member after rotating the second cam member, perform a main washing operation, and, in response to a selection of a new washing course being received by the input device after a completion of the main washing operation, rotate the second cam member one time in the forward direction so as to discharge one solid detergent from the second storage compartment.

According to an embodiment of the disclosure, the processor may be configured to, in response to a selection of a first mode among the washing course being received by the input device, control the first ejector to discharge the one solid detergent from the first storage compartment.

According to an embodiment of the disclosure, the processor may be configured to, in response to a selection of a second mode among the washing course being received by the input device, control the second ejector to discharge one solid detergent from the second storage compartment.

According to an embodiment of the disclosure, the processor may be configured to, in response to determining that additional input of a solid detergent is required during the first mode, control the second ejector to discharge one solid detergent from the second storage compartment.

According to an embodiment of the disclosure, a control method of a dishwasher including a tub, a door to open and close the tub, an input device to receive a selection of a washing course, an automatic detergent dispenser including a storage compartment in which a plurality of solid detergents are stackable so as to be loaded in a vertical direction when the tub is closed by the door, an ejector to discharge a solid detergent, among the plurality of solid detergents loaded in the storage compartment, outside of the storage compartment, a seating member on which a solid detergent discharged from the storage compartment is seatable, and a detector to detect whether a solid detergent is seated on the seating member, includes receiving a selection of a washing course through the input device; controlling the ejector to operate so that, when a plurality of solid detergents are loaded in the storage compartment, one solid detergent among the plurality of solid detergents is discharged outside of the storage compartment to be seated on the seating member; and determining whether a solid detergent is seated on the seating member based on a detection result of the detector.

According to an embodiment of the disclosure, the ejector may include a cam member configured to rotate to move the one solid detergent outside of the storage compartment, and the controlling of the ejector may include rotating the cam member one time in a forward direction to discharge the one solid detergent outside of the storage compartment.

According to an embodiment of the disclosure, the control method may further include rotating the cam member a second time in response to determining that a solid detergent is not seated on the seating member.

According to an embodiment of the disclosure, the control method may further include determining whether a solid detergent is seated on the seating member after rotating the cam member the second time; in response to determining that a solid detergent is not seated on the seating member after rotating the cam member the second time, determining that a solid detergent is not present in the storage compartment; and generating a control signal to provide a notification that a solid detergent is not present in the storage compartment.

According to an embodiment of the disclosure, the control method may further include inputting a solid detergent seated on the seating member into the tub by opening a seating member door at a stage of supplying water for a main washing operation.

According to an embodiment of the disclosure, the control method may further include determining whether an error in discharging the one solid detergent occurred based on the detection result of the detector.

According to an embodiment of the disclosure, the control method may further include rotating the cam member in a reverse direction in response to determining that the error occurred.

According to an embodiment of the disclosure, the control method may further include determining whether an error in discharging the one solid detergent occurred based on power consumption or rotational speed of a motor inside the ejector.

BRIEF DESCRIPTION OF THE DRAWINGS

These and/or other embodiments of the disclosure will become apparent and more readily appreciated from the following description of embodiments, taken in conjunction with the accompanying drawings of which:

FIG. 1 is a perspective view of a state in which a door of a dishwasher according to an embodiment of the disclosure is opened;

FIG. 2 is a schematic side cross-sectional view of the dishwasher according to an embodiment of the disclosure;

FIG. 3 is a perspective view illustrating a state in which a detergent is loaded into an automatic detergent dispenser of the dishwasher according to an embodiment of the disclosure;

FIG. 4 is an exploded perspective view of the automatic detergent dispenser of the dishwasher according to an embodiment of the disclosure;

FIG. 5 is an exploded perspective view of the automatic detergent dispenser of the dishwasher according to an embodiment of the disclosure when viewed from another angle;

FIG. 6 is a perspective view of a state in which some components of the automatic detergent dispenser of the dishwasher according to an embodiment of the disclosure are removed;

FIG. 7 is an enlarged perspective view of some components of the automatic detergent dispenser of the dishwasher according to an embodiment of the disclosure;

FIG. 8 is a view illustrating a state in which some components of the automatic detergent dispenser of the dishwasher according to an embodiment of the disclosure are removed;

FIG. 9 is a view illustrating a state in which a solid detergent loaded in a first storage compartment is discharged from the first storage compartment of FIG. 8;

FIG. 10 is a view illustrating a state in which the solid detergent of FIG. 9 is seated on a seating member;

FIG. 11 is a view illustrating a state in which the solid detergent of FIG. 10 is discharged from the automatic detergent dispenser;

FIG. 12 is a view illustrating a state in which a solid detergent loaded in a second storage compartment is discharged from the second storage compartment of FIG. 8;

FIG. 13 is a view illustrating a state in which some components of the automatic detergent dispenser of the dishwasher according to an embodiment of the disclosure are removed;

FIG. 14 is a view illustrating a state in which some components of the automatic detergent dispenser of the dishwasher according to an embodiment of the disclosure are removed;

FIG. 15 is a view illustrating a state in which an adjusting member of the second storage compartment is moved in FIG. 14;

FIG. 16 is a control diagram of the dishwasher according to an embodiment of the disclosure;

FIG. 17 is a view illustrating a state in which a solid detergent is not present in the storage compartment according to an embodiment of the disclosure;

FIG. 18 is a view illustrating a state in which the solid detergent is discharged from the automatic detergent dispenser according to an embodiment of the disclosure;

FIG. 19 is a view illustrating a state in which an error in discharging a solid detergent occurs according to an embodiment of the disclosure;

FIG. 20 is a control diagram of the dishwasher according to an embodiment of the disclosure;

FIG. 21 is a control diagram of the dishwasher according to an embodiment of the disclosure;

FIG. 22 is a flowchart of a control method of the dishwasher according to an embodiment of the disclosure; and

FIG. 23 is a flowchart of a control method of the dishwasher according to an embodiment of the disclosure.

DETAILED DESCRIPTION

Embodiments described in the disclosure and configurations shown in the drawings are merely examples of the embodiments of the disclosure, and may be modified in various different ways at the time of filing of the present application to replace the embodiments and drawings of the disclosure.

In addition, the same reference numerals or signs shown in the drawings of the disclosure indicate elements or components performing substantially the same function.

Also, the terms used herein are used to describe the embodiments and are not intended to limit and/or restrict the disclosure. The singular forms “a,” “an” and “the” are intended to include the plural forms as well, unless the context clearly indicates otherwise. In this disclosure, the terms “including”, “having”, and the like are used to specify features, numbers, steps, operations, elements, components, or combinations thereof, but do not preclude the presence or addition of one or more of the features, elements, steps, operations, elements, components, or combinations thereof.

It will be understood that when an element is referred to as being “connected” or “coupled” to another element, it can be directly or indirectly connected or coupled to the other element.

It will be understood that, although the terms first, second, third, etc., may be used herein to describe various elements, but elements are not limited by these terms. These terms are only used to distinguish one element from another element. For example, without departing from the scope of the disclosure, a first element may be termed as a second element, and a second element may be termed as a first element. The term of “and/or” includes a plurality of combinations of relevant items or any one item among a plurality of relevant items.

Throughout the description, when an element is “on” another element, this includes not only when the element is in contact with the other element, but also when there is another element between the two elements.

The terms “up and down direction”, “height direction”, “vertical direction”, etc., used in the following description may refer to the Z-direction based on a perspective view of a dishwasher in FIG. 1, and “horizontal direction” may refer to any direction along the X-Y plane in the X-direction or the Y-direction based on the perspective view of FIG. 1.

The terms “first direction”, “second direction”, “third direction”, etc. used in the following description are arbitrarily defined according to some standards to be described later, but are not limited thereto. In addition, “first direction”, “second direction”, and “third direction” may mean a direction comprehensively including all “first direction and opposite direction of first direction”, “second direction and opposite direction of second direction”, and “third direction and opposite direction of third direction”.

Hereinafter “dish” may be used as a concept encompassing bowls, cups, cutlery, and various cooking utensils.

Embodiments of the disclosure may provide a dishwasher capable of storing a plurality of solid detergents and automatically inputting the solid detergent at a necessary time during washing, and a control method thereof.

Embodiments of the disclosure may provide a dishwasher capable of increasing convenience of use by automatically detecting the presence or absence of stored solid detergent

and by automatically detecting a solid detergent being stuck, and by providing feedback thereto, and a control method thereof.

Embodiments of the disclosure may provide a dishwasher capable of inputting an appropriate amount of detergent by preventing over-input of detergent by storing and inputting different sizes of solid detergents by varying a size of a storage compartment, and a control method thereof.

Reference will now be made in detail to embodiments of the disclosure, examples of which are illustrated in the accompanying drawings.

FIG. 1 is a perspective view of a state in which a door of a dishwasher according to an embodiment is opened, FIG. 2 is a schematic side cross-sectional view of the dishwasher according to an embodiment, and FIG. 3 is a perspective view illustrating a state in which a detergent is loaded into an automatic detergent dispenser of the dishwasher according to an embodiment.

A dishwasher 1 may include a tub 12 arranged inside a main body 10. The tub 12 may be formed in a substantially box shape. One side of the tub 12 may be opened. The tub 12 may include an opening 12a. For example, a front surface of the tub 12 may be opened toward the first direction X.

The dishwasher 1 may further include a door 20 configured to open and close the opening 12a of the tub 12. The door 20 may be installed in the main body to open and close the opening 12a of the tub 12. The door 20 may be rotatably installed in the main body 10 through a member such as a hinge 25. The door 20 may be removably mounted to the main body 10.

For example, the door 20 may be rotatably hinged to a lower portion of the main body 10. A rotation axis of the hinge 25 may extend in the second direction Y, which is the left and right direction of the main body 10, to allow the door 20 to be rotated in the front and rear directions in front of the main body 10.

For example, on the front side of the main body 10, the door 20 may be hinged to a hinge arranged on the left or right side of the main body 10 with respect to the second direction Y. The door 20 may be provided to be rotated from the second direction Y to the first direction X by the hinge arranged on the left and/or right side of the main body 10.

The door 20 may include an outer surface 22 forming an exterior of the dishwasher 1 together with the main body 10, and an inner surface 21 facing the inside of the tub 12 when the door 20 closes the tub 12.

The dishwasher 1 may further include a storage container arranged in the tub 12 to accommodate dishes. The storage container may include a plurality of baskets 51, 52 and 53.

The storage container may include an intermediate basket 52 positioned in the middle with respect to the height direction of the dishwasher 1, and a lower basket 51 positioned in a lower portion with respect to the height direction of the dishwasher 1. The intermediate basket 52 may be provided to be supported by an intermediate guide rack 13b. The lower basket 51 may be provided to be supported by a lower guide rack 13a. The intermediate guide rack 13b and the lower guide rack 13a may be installed on a side surface 12d of the tub 12 so as to be slidable toward the opening 12a of the tub 12. The side surface 12d of the tub 12 may include an inner surface of a right wall and an inner surface of a left wall of the tub 12.

Relatively large dishes may be stored in the lower basket 51 and the intermediate basket 52. However, the types of dishes accommodated in the lower and intermediate baskets 51 and 52 is not limited to relatively large dishes. That is, the

plurality of baskets 51, 52 and 53 may accommodate not only relatively large dishes but also relatively small dishes.

The storage container may include an upper basket 53 positioned in an upper portion with respect to the height direction of the dishwasher 1. The upper basket 53 may be formed in a rack assembly to accommodate relatively small dishes. For example, the upper basket 53 may accommodate a cooking utensil such as a ladle, a knife, or a turner, or cutlery. In addition, the rack assembly may accommodate a small cup such as an espresso cup. However, the types of dishes accommodated in the upper basket 53 is not limited thereto.

The upper basket 53 may be provided to be supported by an upper guide rack. The upper guide rack may be installed on the side surface 12d of the tub 12. For example, the upper basket 53 may be slidably moved by the upper guide rack, and inserted into or withdrawn from a washing chamber C.

The storage container is not limited to the shape shown in FIGS. 1 and 2, and the storage container may not include the upper basket 53 according to the size of the tub 12. For example, the storage container may be implemented with the intermediate basket 52 and the lower basket 53.

The dishwasher 1 may include the washing chamber C, which is a space formed inside the tub 12. The washing chamber C may be defined as an inner space of the tub 12. The washing chamber C may correspond to a space surrounded by a lower surface 12b, an upper surface 12c and the side surface 12d of the tub 12, and the inner surface 21 of the door 20 when the door 20 closes the tub 12.

The washing chamber C may refer to a space in which dishes placed in the baskets 51, 52 and 53 are washed by wash water and dried.

The dishwasher 1 may include a spray device 40 configured to spray wash water. The spray device 40 may receive wash water from a sump assembly 70.

The spray device 40 may include a plurality of spray units 41, 42, and 43.

For example, the plurality of spray units 41, 42, and 43 may include a first spray unit 41 arranged under the lower basket 51 in the height direction of the dishwasher 1, a second spray unit 42 arranged under the intermediate basket 52 in the height direction of the dishwasher 1, and a third spray unit 43 arranged above the upper basket 53 in the height direction of the dishwasher 1.

Each of the plurality of spray units 41, 42, and 43 may be configured to spray wash water while rotating. Each of the first spray unit 41, the second spray unit 42, and the third spray unit 43 may be provided to spray wash water while rotating. The plurality of spray units 41, 42 and 43 may be referred to as a plurality of spray rotors. The first spray unit 41, the second spray unit 42, and the third spray unit 43, respectively, may be referred to as a first spray rotor 41, a second spray rotor 42, and a third spray rotor 43.

However, the spray device 40 may spray the wash water in a manner different from the above-described example. For example, unlike the second spray unit 42 and the third spray unit 43, the first spray unit 41 may be fixed to one side of the lower surface 12b of the tub 12. The first spray unit 41 may be configured to spray the wash water in a substantially horizontal direction by a fixed nozzle. A direction of the wash water, which is sprayed in a substantially horizontal direction from the nozzle of the first spray unit 41, may be changed by a conversion assembly (not shown) arranged thereon and then the wash water may move upward. The conversion assembly may be installed on a rail by a holder

and may be provided to be movable in translation along the rail.

The dishwasher 1 may include the sump assembly 70.

The sump assembly 70 may be provided to receive wash water. The sump assembly 70 may collect wash water of the washing chamber C. For example, the lower surface 12b of the tub 12 may be inclined downward toward the sump assembly 70 to smoothly collect water to the sump assembly 70. The wash water of the washing chamber C may flow along the slope of the lower surface 12b of the tub 12 and smoothly flow into the sump assembly 70.

The sump assembly 70 may include a circulation pump 30 configured to pump wash water stored in the sump assembly 70 to the spray device 40.

The sump assembly 70 may include a drain pump 60 configured to drain wash water and foreign substances (e.g., food residues) remaining in the sump assembly 70.

The sump assembly 70 may pump the collected wash water and supply the wash water to the spray device 40. The sump assembly 70 may be connected to the spray device 40 to supply wash water to the spray device 40.

The sump assembly 70 may be independently connected to the first spray unit 41, the second spray unit 42, and the third spray unit 43. For example, the sump assembly 70 may be independently connected to connectors connected to the first spray unit 41, the second spray unit 42, and the third spray unit 43. The connector may be provided in the shape of a connection port, duct, or the like.

For example, the second spray unit 42 and the third spray unit 43 may be provided with one connector, and in this case, wash water supplied through the one connector may flow into a connector. Wash water flowing into the connector may be branched during moving, and the branched wash water may be provided to at least one of the second spray unit 42 and the third spray unit 43.

The dishwasher 1 may include an alternating device (not shown) configured to selectively supply wash water to the spray device 40. The alternating device (not shown) may be driven to selectively supply wash water to each connector connected to each of the spray devices 41, 42, and 43. For example, the alternating device (not shown) may selectively supply wash water to at least one of a connector connected to the first spray device 41 and a connector connected to the second spray device 42.

The dishwasher 1 may include a machine room L, which is a space provided below the tub 12. The machine room L may be a place in which a component for circulating wash water is disposed.

For example, at least a part of the sump assembly 70 may be arranged in the machine room L. Most of the sump assembly 70 may be arranged in the machine room L. As for a volume of the sump assembly 70, a volume of the sump assembly 70 located in the washing chamber C may be less than a volume of the sump assembly 70 located in the machine room L. By reducing the volume of the sump assembly 70 occupying the washing chamber C, the volume of the washing chamber C may be secured. Accordingly, a capacity of the washing chamber C may be increased, and thus a storage capacity of the dishes may be improved.

The dishwasher 1 may include an automatic detergent dispenser 1000 configured to input a solid detergent into the tub 12. The dishwasher 1 may include a detergent box 90 provided to input not only a solid detergent but also powder detergent or liquid detergent into the tub 12.

When a user inputs information related to a washing mode of the dishwasher 1 through an inputter of the dishwasher 1 or a mobile device, a control device 1900, which will be

described later, may control the dishwasher 1 to selectively input the detergent stored in the detergent box 90 into the tub 12 based on the user input obtained from a main control device. The information related to the washing mode may include information related to a small amount washing mode in which a small number of dishes is washed or information related to a quick washing mode in which a washing time is minimized. The solid detergent means a solid detergent that is formed to have a predetermined shape. The solid detergent may have an approximate block shape, and thus the solid detergent may be referred to by various terms such as detergent block and block-type detergent. The shape of the solid detergent is not limited to a specific shape or size, and may have various shapes.

The automatic detergent dispenser 1000 may be provided to allow a plurality of solid detergents to be loaded. The automatic detergent dispenser 1000 may be provided to allow one of a plurality of solid detergents to be input into the tub 12 while the dishwasher 1 washes dishes.

For example, the dishwasher 1 may be provided to wash dishes through a pre-washing operation, a main washing operation, a rinsing operation, and a drying operation. The automatic detergent dispenser 1000 may be configured to input a solid detergent into the tub 12 before or at the start of the main washing operation.

The detergent box 90 may be provided to accommodate powder detergent or liquid detergent. The detergent box 90 may be provided to allow detergent to be input into the tub 12 while the dishwasher 1 washes dishes.

The dishwasher 1 may be configured to allow one detergent, which is selected by a user between detergent stored in the detergent box 90 and solid detergents loaded in the automatic detergent dispenser 1000, to be input to the tub 12.

The automatic detergent dispenser 1000 may be disposed on the inner surface 21 of the door 20. The automatic detergent dispenser 1000 may be provided to be coupled to the inner surface 21 of the door 20.

The detergent box 90 may be disposed on the inner surface 21 of the door 20. When the door 20 closes the tub 12, the automatic detergent dispenser 1000 and the detergent box 90 may be arranged in the third direction Z, which is the vertical direction when the door 20 closes the tub 12.

Because the automatic detergent dispenser 1000 is disposed on the door 20, the automatic detergent dispenser 1000 may be provided to be rotated together with the door 20 by the rotation of the door 20.

When a position in which the door 20 closes the tub 12 is defined as a first position 20A of the door 20, and a position in which the door 20 opens the tub 12 is defined as a second position 20B of the door 20, the door 20 may be configured to open and close the tub 12 by moving between the first position 20A and the second position 20B.

The second position 20B of the door 20 may be defined as any position among positions at which the door 20 opens the tub 12, and it is appropriate that the second position 20B is a position in which dishes stored in the tub 12 are allowed to be withdrawn to the outside of the tub 12. For example, the second position 20B of the door 20 may be a position in which an extension direction of the inner surface 21 of the door 20 corresponds to the first direction X.

The automatic detergent dispenser 1000 may be interlocked with the door 20 so as to be moved between a first position 1000A of the automatic detergent dispenser 1000 corresponding to the first position 20A of the door 20, and a second position 1000B of the automatic detergent dispenser 1000 corresponding to the second position 20B of the door 20.

11

When the door 20 closes the tub 12, the automatic detergent dispenser 1000 may be disposed at the first position 1000A, and when the door 20 opens the tub 12, the automatic detergent dispenser 1000 may be disposed at the second position 1000B.

As illustrated in FIG. 3, a user can load a plurality of solid detergents into the automatic detergent dispenser 1000 when the automatic detergent dispenser 1000 is disposed at the second position 1000B.

A user can open a storage compartment cover 1140 of the automatic detergent dispenser 1000 and load a plurality of solid detergents into a storage compartment 1200.

In the conventional manner, whenever the dishwasher washes dishes, a user has to load the detergent into the automatic detergent dispenser or the detergent box, which causes inconvenience to the user. On the other hand, the automatic detergent dispenser 1000 of the dishwasher 1 according to an embodiment may be configured to allow a plurality of solid detergents to be loaded into the automatic detergent dispenser 1000 at the one-time loading by a user, and when the dishwasher 1 performs the washing process, one solid detergent among the plurality of solid detergents may be input into the tub 12 for one time-washing process.

Because a plurality of solid detergents remains inside the automatic detergent dispenser 1000 during the washing process of the dishwasher 1, moisture may flow into the automatic detergent dispenser 1000 during the washing process, and accordingly, the plurality of solid detergents may be damaged.

Because the automatic detergent dispenser 1000 is moved between the first position 1000A and the second position 1000B, a plurality of solid detergents loaded in the automatic detergent dispenser 1000 may be separated from the stored position.

Hereinafter the automatic detergent dispenser 1000 capable of relieving the above difficulties will be described in detail.

FIG. 4 is an exploded perspective view of the automatic detergent dispenser of the dishwasher according to an embodiment, FIG. 5 is an exploded perspective view of the automatic detergent dispenser of the dishwasher according to an embodiment when viewed from another angle, FIG. 6 is a perspective view of a state in which some components of the automatic detergent dispenser of the dishwasher according to an embodiment are removed, FIG. 7 is an enlarged perspective view of some components of the automatic detergent dispenser of the dishwasher according to an embodiment, and FIG. 8 is a view illustrating a state in which some components of the automatic detergent dispenser of the dishwasher according to an embodiment are removed.

As illustrated in FIGS. 4 and 5, the automatic detergent dispenser 1000 may include a housing 1100.

The housing 1100 may include a first housing 1110 forming the storage compartment 1200 to be described later and a second housing 1120 coupled to the first housing 1110.

The first housing 1110 may be provided to be coupled to the inner surface 21 of the door 20.

The second housing 1120 may be coupled to the first housing 1110 in the first direction X when the automatic detergent dispenser 1000 is disposed at the first position 1000A.

The second housing 1120 may form the storage compartment 1200 together with the first housing 1110. The second housing 1120 may include a storage compartment opening 1121 provided to open the storage compartment 1200 to the outside. The second housing 1120 may include an inlet 1122

12

communicating with a seating member 1400 to be described later and configured to allow a solid detergent to be discharged from the automatic detergent dispenser 1000 and input into the tub 12.

5 The housing 1100 may include an intermediate housing 1130 disposed between the first housing 1110 and the second housing 1120 and provided to support an ejector 1300 and the like disposed inside the housing 1100.

For example, components such as the ejector 1300 may be seated on the first housing 1110 and supported by the intermediate housing 1130. Alternatively, components such as the ejector 1300 may be seated on the second housing 1120 and supported by the intermediate housing 1130.

For example, the intermediate housing 1130 may be integrally formed with the first housing 1110. Alternatively, the intermediate housing 1130 may be integrally formed with the second housing 1120.

The housing 1100 may include the storage compartment cover 1140 disposed on the second housing 1120 and configured to open and close the storage compartment opening 1121.

The housing 1100 may include an inlet cover 1150 disposed on the second housing 1120 and configured to open and close the inlet 1122.

25 The first housing 1110 may include a control device seating member 1111 disposed in a direction opposite to the direction in which the first housing 1110 is coupled to the second housing 1120, and on which the control device 1900 configured to control the automatic detergent dispenser 1000 is seated.

For example, the control device seating member 1111 may be disposed on an outer side of an inside of the housing 1100 formed by coupling the second housing 1120 to the first housing 1110. For example, the control device seating member 1111 may be disposed inside the housing 1100 formed by coupling the second housing 1120 to the first housing 1110.

35 The first housing 1110 may include a control device cover 1112 covering the control device seating member 1111 from the outside. The control device cover 1112 is not disposed in the inner space of the housing 1100, which is formed by the combination of the first and second housings 1110 and 1120, but is disposed outside the inner space of the housing 1100. Accordingly, when it is required to replace the control device 1900, the control device 1900 may be easily replaced without disassembling the first and second housings 1110 and 1120.

40 The control device 1900 may control the driving of the ejector 1300 and a seating member door 1410, which will be described later, and may control the automatic detergent dispenser 1000 based on sensing values of various sensors.

45 The control device 1900 may be configured to communicate with the main control device of the dishwasher 1. For example, the control device 1900 and the main control device may constitute a controller of the dishwasher 1.

The main control device may obtain a user input through an inputter of the dishwasher 1 or a mobile device, and may control driving of the dishwasher 1 based on the obtained user input.

50 The main control device may transmit information about the received user input to the control device 1900. The control device 1900 may control the automatic detergent dispenser 1000 based on information about the input received from the main control device.

55 The automatic detergent dispenser 1000 may include a wire W electrically connecting the control device 1900 to electronic components configured to drive the automatic

13

detergent dispenser **1000**. The wire **W** may electrically connect the electronic components (a driving motor **1320**, a seating member door driver **1470** and various sensors) configured to drive the automatic detergent dispenser **1000** to allow one of the plurality of solid detergents loaded in the storage compartments **1200** and **1200'** to be input into the tub **12**, and the control device **1900**.

For example, the wire **W** may electrically connect the main control device and a power supplier of the dishwasher **1** to the control device **1900**. For example, the wire **W** may be provided to electrically connect only some of components such as various electronic components and the control device **1900** of the automatic detergent dispenser **1000** or the main control device of the dishwasher **1**.

For example, at least some of components of various electronic components, sensors and the control device **1900** of the automatic detergent dispenser **1000** or the main control device of the dishwasher **1** may be configured to transmit and receive signals to each other by wireless communication without being electrically connected through the wire **W**.

The control device **1900** may control the automatic detergent dispenser **1000** based on values sensed by various sensors of the automatic detergent dispenser **1000**. This will be described later in detail.

As illustrated in FIGS. **6** to **8**, the automatic detergent dispenser **1000** may include the storage compartment **1200** in which a plurality of solid detergents is loaded.

When the automatic detergent dispenser **1000** is disposed at the first position **1000A**, the storage compartment **1200** may be provided to allow a plurality of solid detergents to be stacked in the third direction **Z** corresponding to the vertical direction. For example, the storage compartment **1200** may be provided with the plurality of storage compartments **1200** and **1200'**. However, for convenience of description, a single storage compartment **1200** will be described.

The storage compartment **1200** may correspond to a space formed by the first housing **1110** and the second housing **1120**. In order to allow the plurality of solid detergents to be stacked and loaded in the third direction **Z**, the storage compartment **1200** may be provided with a space including a long side **1201** extending in the third direction **Z** when the automatic detergent dispenser **1000** is disposed at the first position **1000A**.

For example, the storage compartment **1200** may be provided as a space formed by the first housing **1110**. Alternatively, the storage compartment **1200** may be provided as a space formed by the second housing **1120**.

When the storage compartment cover **1140** opens the storage compartment opening **1121**, the storage compartment **1200** may be opened to the outside through the storage compartment opening **1121**. As shown in FIG. **3**, when the automatic detergent dispenser **1000** is placed at the second position **1000B**, a user can open the storage compartment cover **1140** and input a plurality of solid detergents into the storage compartment **1200** so as to load the plurality of solid detergents into the storage compartment **1200**.

The automatic detergent dispenser **1000** is disposed on the inner surface **21** of the door **20**, and thus when the door **20** is opened, the automatic detergent dispenser **1000** may be disposed outside the washing chamber **C** and thus a user can easily input the detergent.

The storage compartment **1200** may have a predetermined volume or more to store a plurality of solid detergents. As described above, the automatic detergent dispenser **1000** is disposed on the inner surface **21** of the door **20**, and thus

14

when a volume of the storage compartment **1200** increases in the first direction **X**, a volume of the washing chamber **C** may be reduced. In order to prevent the volume of the storage compartment **1200** from increasing in the first direction **X**, the storage compartment **1200** may be provided to allow a plurality of solid detergents to be stacked in the third direction **Z** corresponding to the vertical direction when the automatic detergent dispenser **1000** is at the first position **1000A**.

When the automatic detergent dispenser **1000** is disposed at the first position **1000A**, the plurality of solid detergents may be loaded in the storage compartment **1200** so as to be stacked and arranged only in the third direction **Z** without being arranged in the first direction **X**.

The storage compartment **1200** may be formed to allow the plurality of solid detergents to be stacked only in the third direction **Z**. Accordingly, it is possible to maximally secure the space of the washing chamber **C** with respect to the first direction **X** as described above, and it is possible to secure the space of the storage compartment **1200** of the automatic detergent dispenser **1000** with respect to the second direction **Y**.

The storage compartment **1200** may be formed to allow a plurality of solid detergents to be stacked only in the third direction **Z**, and thus a driving configuration of the ejector **1300** such as a transmission member **1330** of the automatic detergent dispenser **1000** or an electronic configuration such as the control device **1900** may be arranged in the second direction **Y** in the storage compartment **1200**.

Accordingly, the volume of the automatic detergent dispenser **1000** in the second direction **Y** may be minimized.

Accordingly, on the inner surface **21** of the door **20**, an additional component other than the automatic detergent dispenser **1000** may be disposed outside the automatic detergent dispenser **1000** in the second direction **Y**, and thus a ratio of the volume of the inner space of the tub **12** to the volume of the main body **10** of the dishwasher **1** may be increased.

However, it is not limited thereto, and a plurality of solid detergents may be loaded in the storage compartment **1200** to be stacked and arranged only in the second direction **Y**, which is the left and right direction, when the automatic detergent dispenser **1000** is disposed at the first position **1000A**.

The automatic detergent dispenser **1000** may include the ejector **1300** configured to move one of the plurality of solid detergents, which is loaded on the storage compartment **1200**, to the outside of the storage compartment **1200** so as to be discharged from the storage compartment **1200**. For example, the ejector **1300** may be provided with a plurality of ejectors **1300** and **1300'** corresponding to the number of the plurality of storage compartments **1200** and **1200'**. However, for convenience of description, it will be described based on a single ejector **1300**.

When the automatic detergent dispenser **1000** is disposed at the first position **1000A**, the ejector **1300** may be configured to allow a single solid detergent, which is disposed at the lowest position in the third direction **Z** among the plurality of solid detergents stacked in the third direction **Z**, to be discharged to the outside of the storage compartment **1200**.

The ejector **1300** may be disposed on one side **1201a** of the long side **1201** with respect to an extension direction of the long side **1201**. When the automatic detergent dispenser **1000** is disposed at the first position **1000A**, the one side **1201a** of the long side **1201** may be disposed on a lower side

in the third direction Z, and the other side **1201b** of the long side **1201** may be disposed on an upper side.

The ejector **1300** may be disposed below the storage compartment **1200** with respect to the third direction Z to allow a single solid detergent, which is disposed at the lowest position in the third direction Z among the plurality of solid detergents stacked in the third direction Z, to be discharged from the storage compartment **1200**.

When the automatic detergent dispenser **1000** is disposed at the first position **1000A**, the ejector **1300** may discharge a solid detergent, which is closest to a lower surface **1220** of the storage compartment **1200** among the plurality of solid detergents, to the outside of the storage compartment **1200**.

For example, the ejector **1300** may be configured to press the solid detergent seated on the lower surface **1220** of the storage compartment **1200** among the plurality of solid detergents. That the solid detergent is seated on the lower surface **1220** means that the solid detergent is supported by the lower surface **1220** or that the solid detergent is placed in contact with the lower surface **1220**. Accordingly, that the solid detergent is seated on the lower surface **1220** means that the solid detergent is placed in a position in which the solid detergent is pressed and then discharged from the storage compartment **1200** by the ejector **1300**.

The storage compartment **1200** may include a storage compartment outlet **1210** provided to discharge one solid detergent to the outside of the storage compartment **1200** by the ejector **1300**.

The storage compartment outlet **1210** may be arranged below the storage compartment **1200** to allow one solid detergent, which is disposed at the lowest position in the third direction Z among the plurality of solid detergents stacked in the third direction Z, to be discharged to the outside of the storage compartment **1200**.

The storage compartment outlet **1210** and the ejector **1300** may be disposed below the storage compartment **1200** so as to discharge one solid detergent disposed at the lowest position among the plurality of solid detergents stacked in the third direction Z to the outside of the storage compartment **1200**.

The storage compartment **1200** is provided to allow a plurality of solid detergents to be stacked in the third direction Z, and thus when the lowest solid detergent among the plurality of solid detergents is discharged to the outside of the storage compartment **1200**, the plurality of solid detergents may be moved downward in the stacking direction by gravity.

Because all of the plurality of solid detergents is moved downward, the solid detergent, which is disposed directly above the solid detergent discharged to the outside of the storage compartment **1200**, may be moved adjacent to the lower surface **1220** of the storage compartment **1200** and then disposed in a space in which the discharged solid detergent was located. The solid detergent may be discharged to the outside of the storage compartment **1200** by the ejector **1300** in the next washing process of the dishwasher **1**.

That is, when the automatic detergent dispenser **1000** is disposed at the first position **1000A**, the storage compartment **1200** may be provided to allow a plurality of solid detergents to be stacked in the third direction Z, and the ejector **1300** may be arranged on the lower side of the storage compartment **1200**. Accordingly, the plurality of solid detergents may be discharged to the outside of the storage compartment **1200** in the stacking order from the lowest solid detergent in the third direction Z.

However, the ejector **1300** is not limited thereto, and the ejector **1300** may be configured to discharge one solid detergent, which is disposed at the highest position in the third direction Z among the plurality of solid detergents stacked in the third direction Z, from the storage compartment **1200**.

As shown in FIG. 7, when a solid detergent D has a shape in which a horizontal length **d1** and a vertical length **d2** are greater than a height **h**, the solid detergent D may be loaded on the storage compartment **1200** to be stacked in the height **h** direction in the storage compartment **1200**.

As for the solid detergent D described below, it is assumed that the horizontal length **d1** is greater than the vertical length **d2** and the height **h**.

For example, the solid detergent D may be loaded in the storage compartment **1200** in such a way that a direction formed by the smallest length among the horizontal length **d1**, the vertical length **d2**, and the height **h** of the solid detergent D corresponds to the stacking direction of the plurality of solid detergents.

This is to maximize the number of solid detergents D that may be loaded into the storage compartment **1200**.

For example, when the automatic detergent dispenser **1000** is disposed at the first position **1000A**, the solid detergent D may be loaded in the storage compartment **1200** in such a way that a surface of the solid detergent D formed in the horizontal length **d1** and the vertical length **d2** directions corresponds to a cross-sectional area **S** of the storage compartment **1200** formed in the first direction X and the second direction Y.

For example, the plurality of solid detergents D may be stacked inside the storage compartment **1200** with respect to the height **h** direction of the solid detergent D.

The solid detergent may have various sizes according to components, functions, or manufacturing companies of the solid detergent, but a volume of the solid detergent may be determined in proportion to the volume of the washing chamber of the dishwasher. Because the volume of the washing chamber is provided within a predetermined range, the volume of the solid detergent may also be provided within a predetermined range, and accordingly, the horizontal length, the vertical length, and the height of the solid detergent may be similarly designed regardless of the types of the solid detergent.

A solid detergent D described below may be defined as a suitable solid detergent D that may be loaded into the automatic detergent dispenser **1000** of the dishwasher **1** according to an embodiment, and the horizontal length **d1**, the vertical length **d2**, and the height **h** of the solid detergent D may be defined as an approximate value of a horizontal length, a vertical length, and a height of various solid detergents that may be loaded into the automatic detergent dispenser **1000** of the dishwasher **1**. Further, the horizontal length **d1**, the vertical length **d2**, and the height **h** of the solid detergent D may be defined as a changeable value within a predetermined range. For example, the horizontal length **d1** and the vertical length **d2** may be defined based on dimensions provided in the first direction X and the second direction Y, and the horizontal length may also be defined as **d2**, and the vertical length may also be defined as **d1**.

An area **S** of the storage compartment **1200** (hereinafter it is referred to as a cross-sectional area of the storage compartment **1200**) in the first direction X and the second direction Y in a state in which the automatic detergent dispenser **1000** is disposed at the first position **A** may be provided as a size in which the solid detergent D is easily loaded and stacked in the third direction Z.

The cross-sectional area S of the storage compartment 1200 may be formed by a pair of sides having a horizontal length L1 extending in the second direction Y and a pair of sides having a vertical length L2 extending in the first direction X when the automatic detergent dispenser 1000 is disposed at the first position A. For example, the horizontal length L1 and the vertical length L2 may be defined based on the dimension provided in the first direction X and the second direction Y, and the horizontal length may also be defined as L2, and the vertical length may also be defined as L1.

The horizontal length L1 of the cross-sectional area S of the storage compartment 1200 may be a length in the second direction Y between a right surface 1230 and a left surface 1240 of the storage compartment 1200, and the vertical length L2 of the cross-sectional area S of the storage compartment 1200 may be a length in the first direction X between an inner surface 1260 and the storage compartment opening 1121 of the storage compartment 1200.

When the solid detergent D is loaded into the storage compartment 1200, the solid detergent D may be arranged to allow one side having the horizontal length d1 of the solid detergent D to correspond to a side having the horizontal length L1 of the cross-sectional area S of the storage compartment 1200, and to allow the other side having the vertical length d2 of the solid detergent D to correspond to a side having the vertical length L2 of the cross-sectional area S of the storage compartment 1200.

As described above, because the vertical length d2 of the solid detergent D is formed to be less than the horizontal length d1, the horizontal length L1 of the cross-sectional area S may be formed to be greater than the vertical length L2. Further, because the horizontal length d1 of the solid detergent is formed to be greater than the length of the height h of the solid detergent D, the vertical length L2 of the cross-sectional area S may be formed to be greater than the height h of the solid detergent D.

The horizontal length L1 of the cross-sectional area S may be greater than the horizontal length d1 of the solid detergent D by approximately 10% to 30% of the horizontal length d1 of the solid detergent D.

The vertical length L2 of the cross-sectional area S may be greater than the vertical length d2 of the solid detergent D by approximately 10% to 30% of the vertical length d2 of the solid detergent D.

In order to allow the plurality of solid detergents to stably descend inside the storage compartment 1200 while maintaining a stacked arrangement when the solid detergent disposed at the lowest position in the third direction Z is moved out of the storage compartment 1200 by the ejector 1300, the cross-sectional area S of the storage compartment 1200 may be formed to have the above-mentioned value.

When the horizontal and vertical lengths L1 and L2 of the cross-sectional area S are formed to be greater than the horizontal and vertical lengths d1 and d2 of the solid detergent D by a length that is less than 10% of the horizontal and vertical lengths d1 and d2 of the solid detergent D, a plurality of solid detergents may be stuck inside the storage compartment 1200 while being moved downward inside the storage compartment 1200. Accordingly, it is difficult for the plurality of solid detergents to be stably moved downward.

For example, when the solid detergent disposed at the lowest position in the third direction Z among the plurality of stacked solid detergents is moved downward, the solid detergent may be stuck on the inside of the storage compartment 1200 without being seated on the lower surface 1220 of the storage compartment 1200.

Accordingly, even when the ejector 1300 is driven, a pressing member 1312a, which will be described later, may not easily press the solid detergent disposed at the lowest position in the third direction Z, and thus the solid detergent may not be discharged from the storage compartment 1200.

When the horizontal and vertical lengths L1 and L2 of the cross-sectional area S are formed to be greater than the horizontal and vertical lengths d1 and d2 of the solid detergent D by a length that is more than 30% of the horizontal and vertical lengths d1 and d2 of the solid detergent D, the detergents may be rotated while being moved downward in the storage compartment 1200, and thus the stacked arrangement of the detergents may be broken.

For example, as the cross-sectional area S is formed to be greater than the solid detergent, the solid detergent may be rotated or moved in an oblique direction with respect to the third direction Z when being moved downward, and thus the solid detergent may be moved in the first direction X and the second direction Y without being moved in the third direction. Accordingly, the stacked arrangement of the plurality of solid detergents may not be maintained.

Therefore, the horizontal and vertical lengths L1 and L2 of the cross-sectional area S may be formed to be greater than the horizontal and vertical lengths d1 and d2 of the solid detergent D by approximately 10% to 30% of the horizontal and vertical lengths d1 and d2 of the solid detergent D.

Because the vertical length L2 of the cross-sectional area S of the storage compartment 1200 is formed to be greater than the vertical length d2 of the solid detergent D, the automatic detergent dispenser 1000 may have a predetermined thickness in the direction in which the vertical length L2 extends.

Accordingly, when the door 20 is disposed at the first position 20A, the automatic detergent dispenser 1000 may protrude from the door 20 toward the inside of the tub 12 in the first direction X and thus the inner space of the tub 12 may be reduced.

Particularly, as for the lower basket 51 disposed at a height substantially corresponding to the automatic detergent dispenser 1000 in the third direction Z, when the door 20 is disposed at the first position 20A, the lower basket 51 may collide with the automatic detergent dispenser 1000 with respect to the first direction X. To prevent this, the automatic detergent dispenser 1000 may be arranged to be spaced apart from the lower basket 51 in the first direction X when the automatic detergent dispenser 1000 is disposed at the first position 1000A. For example, when the automatic detergent dispenser 1000 is disposed at the first position 1000A, the automatic detergent dispenser 1000 may be arranged to be spaced apart from the intermediate basket 52 with respect to the first direction X.

In addition, the door 20 is disposed at the second position 20B, and accordingly, the lower basket 51 may be withdrawn toward the front of the tub 12 in the first direction X. When the lower basket 51 is withdrawn forward, the withdrawal of the lower basket 51 may be limited by the thickness of the automatic detergent dispenser 1000 because the automatic detergent dispenser 1000 has a predetermined thickness in the extension direction of the vertical length L2.

The automatic detergent dispenser 1000 may be provided to be coupled to the inner surface 21 of the door 20. When the automatic detergent dispenser 1000 is coupled to the

inner surface 21, at least a portion of the automatic detergent dispenser 1000 may be inserted into the inside of the door 20 in the first direction X.

Accordingly, when the automatic detergent dispenser 1000 is disposed at the first position 1000A, a predetermined separation distance between the automatic detergent dispenser 1000 and the lower basket 51 may be easily generated in the first direction X.

Accordingly, when the automatic detergent dispenser 1000 is disposed at the second position 1000B, the protrusion of the automatic detergent dispenser 1000 may be minimized in the third direction Z, and thus the lower basket 51 may be easily withdrawn in the first direction X without limitation of the automatic detergent dispenser 1000.

For example, the automatic detergent dispenser 1000 may be coupled to the inner surface 21 of the door 20 in such a way that, when the automatic detergent dispenser 1000 is disposed at the second position 1000B, the upper end of the automatic detergent dispenser 1000 in the third direction Z is positioned lower than the lower end of the lower basket 51 in the third direction Z. Accordingly, when the lower basket 51 slides out of the tub 12 and is withdrawn while the automatic detergent dispenser 1000 is disposed at the second position 1000B, the lower basket 51 may be withdrawn from the tub 12 without colliding with the automatic detergent dispenser 1000.

The ejector 1300 may include a pressing member 1310 configured to press and move one solid detergent, which is disposed at the lowest position in the third direction Z among the plurality of solid detergents stacked in the third direction Z, to the outside of the storage compartment 1200.

The pressing member 1310 may include a cam member configured to be rotated so as to press the solid detergent. Hereinafter the pressing member 1310 will be referred to as a cam member 1310.

The cam member 1310 may include a presser 1312a provided to protrude from a rim of the cam member 1310 and configured to press the solid detergent while being rotated by the rotation of the cam member 1310.

The presser 1312a may be rotated according to the rotation of the cam member 1310 and moved into the storage compartment 1200, and configured to press one solid detergent, which is disposed at the lowest position in the third direction Z among the plurality of solid detergents stacked in the third direction Z, so as to be moved to the outlet 1210.

The cam member 1310 may move the solid detergent by pressing the solid detergent toward the direction of rotation of the cam member 1310.

For convenience of description, the rotation direction and the left and right sides of the cam member 1310 will be described based on the state shown in FIG. 8. The right side in FIG. 8 may be a direction corresponding to the left side in FIG. 1, and the left side in FIG. 8 may be a direction corresponding to the right side in FIG. 1.

Accordingly, the left and right sides in FIG. 1 may be opposite to the left and right sides in FIG. 8 with respect to the second direction Y. However, for convenience of description, it will be described based on the left and right sides shown in FIG. 8.

In addition, the cam member 1310 to be described below will be described as an example of the cam member 1310 of the ejector 1300 disposed on the left side of the second direction Y shown in FIG. 8.

The ejector 1300 may be disposed below the storage compartment 1200, and thus when a rotation direction of the cam member 1310 is a clockwise direction, the cam member 1310 may move a solid detergent, which is seated on the

lower surface 1220 of the storage compartment 1200, to the right side while the cam member 1310 rotates clockwise.

In order to discharge the solid detergent, which is moved to the right side, to the outside of the storage compartment 1200, the storage compartment outlet 1210 may be disposed below the right surface 1230 of the storage compartment 1200.

The storage compartment 1200 may include a penetration member 1221 formed on the lower surface 1220 of the storage compartment 1200 and provided to allow the presser 1312a to be moved from the outside of the storage compartment 1200 to the inside of the storage compartment 1200.

The penetration member 1221 may be provided to extend not only to the lower surface 1220 of the storage compartment 1200 but also to the lower side of the right surface 1230 and the left surface 1240 of the storage compartment 1200.

The presser 1312a may be rotated by the rotation of the cam member 1310 and moved into the storage compartment 1200 through the lower side of the left surface 1240 and the penetration member 1221 of the lower surface 1220, and then moved to the outside of the storage compartment 1200 through the lower side of the right surface 1230 and the penetration member 1221 of the lower surface 1220 according to the rotation of the cam member 1310.

The presser 1312a may be provided to be rotated while pressing the solid detergent seated on the lower surface 1220, so as to allow the solid detergent to be moved to the right side.

The penetration member 1221 may be provided in such a way that at least a portion of the lower surface 1220 is opened, as illustrated in FIG. 7. As at least a portion of the lower surface 1220 is opened, the cam member 1310 disposed below the storage compartment 1200 may be rotated and the presser 1312a may be moved into the storage compartment 1200 through the penetration member 1221.

The penetration member 1221 may be provided in such a way that not all but at least a portion of the lower surface 1220 is opened

For example, an area of a portion, in which the penetration member 1221 is formed, in the lower surface 1220 may be less than an area of a portion, which is closed in the third direction Z, in the lower surface 1220. Hereinafter the lower surface 1222 closed in the third direction Z is referred to as a support surface 1222.

This is because the support surface 1222 supports the solid detergent located at the lowest position in the third direction Z.

For example, the penetration member 1221 may be provided to extend from the center of the lower surface 1220 with respect to the first direction X to the second direction Y. Accordingly, the front and rear sides of the penetration member 1221 with respect to the first direction X may be provided as the support surface 1222.

This is to allow the solid detergent located at the lowest position in the third direction Z to be stably positioned on the lower surface 1220 when the plurality of solid detergents is stacked. The support surface 1222 may support the solid detergent located at the lowest position in the third direction Z to allow the solid detergent to be disposed adjacent to the lower surface 1220, and thus the presser 1312a may easily press the solid detergent while the presser 1312a is moved through the penetration member 1221.

Particularly, the support surface 1222 may be formed in the front and rear of the penetration member 1221 in the first direction X, and the support surface 1222 may allow one solid detergent, which is disposed at the lowest position in

the third direction Z, to be supported by the storage compartment **1200** horizontally in the third direction Z.

Accordingly, when the solid detergent is moved to the outside of the storage compartment **1200** by the presser **1312a**, the solid detergent may be moved in the second direction Y in a substantially horizontal state with respect to the third direction Z.

For example, the support surface **1222** may guide the solid detergent, which is moved in the second direction Y, to be moved in a horizontal state with respect to the third direction Z. Based on FIG. 7, the solid detergent D may be loaded into the storage compartment **1200** in a state in which a lower surface (us) of the solid detergent D in the third direction Z is in contact with the support surface **1222**. When the solid detergent D is pressed toward the second direction Y by the presser **1312a**, the lower surface (us) of the solid detergent D may be guided by the support surface **1222** and then moved to the storage compartment outlet **1210** while the solid detergent D is maintained in a substantially horizontal state with respect to the third direction Z.

When the solid detergent is moved in the second direction Y while being inclined with respect to the third direction Z, the solid detergent may be rotated, or moved to another direction without being moved to the second direction Y by the center of gravity. Accordingly, the solid detergent may not be moved toward the storage compartment outlet **1210** and may not be discharged to the outside of the storage compartment **1200**.

As for the cam member **1310**, the rim of the cam member **1310** with respect to a rotation direction of the cam member **1310** may include a plurality of cam regions that is partitioned in the rotation direction of the cam member **1310**. When a cam region, in which a rim having a shortest radius from a rotating shaft **1313** of the cam member **1310** is disposed, among the plurality of cam regions is defined as a first cam region **1310A1**, the first cam region **1310A1** may be disposed on an upper end of the cam member **1310** when the dishwasher **1** does not perform the washing process.

The presser **1312a** may protrude to a predetermined height in a radial direction of the cam member **1310** with respect to the first cam region **1310A1**.

The presser **1312a** may protrude to a predetermined height in the radial direction of the cam member **1310** with respect to the first cam region **1310A1**, so as to allow a pressing force, which is capable of transferring the solid detergent D to the storage compartment outlet **1210**, to be transferred to the solid detergent D.

The presser **1312a** may protrude to a predetermined height in the radial direction of the cam member **1310** with respect to the first cam region **1310A1**, and thus when the cam member **1310** is rotated, the presser **1312a** may press the solid detergent D, which is disposed at the lowest position in the third direction Z without pressing a solid detergent disposed above the solid detergent D at the lowest position.

For example, the presser **1312a** may protrude by 15 mm in the radial direction of the cam member **1310** with respect to the first cam region **1310A1**.

When the first cam region **1310A1** of the cam member **1310** is disposed on the upper end of the cam member **1310**, the first cam region **1310A1** may be disposed at a lower position than the support surface **1222** in the third direction Z. This is to allow, when the solid detergent located at the lowest position among the plurality of solid detergents is disposed on the lower surface **1220** of the storage compartment **1200**, the solid detergent to be located in the storage compartment **1200** in a substantially horizontal state with

respect to the third direction Z while preventing one side of the solid detergent from being pressed upward with respect to the third direction Z by the cam member **1310**.

A cam member **1310'** of an ejector **1300'** disposed on the right side with respect to the second direction Y shown in FIG. 8 may be configured to be rotatable counterclockwise with respect to the direction shown in FIG. 8. Accordingly, the solid detergent loaded in the storage compartment **1200'** disposed on the right side may be provided to be discharged to the left side of the storage compartment **1200'**. This will be described later in detail.

The rotating shaft **1313** of the cam member **1310** may be provided to extend in the first direction X when the automatic detergent dispenser **1000** is disposed at the first position **1000A**. The cam member **1310** may be disposed in such a way that the radial direction of the cam member **1310** is disposed in a direction perpendicular to the first direction X, and accordingly, when the cam member **1310** is disposed inside the housing **1100**, a volume of the cam member **1310** may be minimized in the first direction X. As described above, this is to maximize the volume of the washing chamber C in the first direction X.

The ejector **1300** may include the driving motor **1320** configured to generate a rotational force to drive the cam member **1310**. The driving motor **1320** may be arranged in such a way that a rotating shaft **1321** of the driving motor **1320** extends in a direction substantially perpendicular to the first direction X when the automatic detergent dispenser **1000** is disposed at the first position **1000A**. Accordingly, when the driving motor **1320** is disposed inside the housing **1100**, a volume of the driving motor **1320** in the first direction X may be minimized. As described above, this is to maximize the volume of the washing chamber C in the first direction X.

The ejector **1300** may include the transmission member **1330** configured to transmit a rotational force generated by the driving motor **1320** to the pressing member **1310**.

The transmission member **1330** may include a plurality of gears. Because the rotating shaft **1313** of the cam member **1310** is arranged to extend in the first direction X and the rotating shaft **1321** of the driving motor **1320** is arranged to extend in a direction perpendicular to the first direction X, the transmission member **1330** may include a worm gear configured to vertically change a transmission direction of the driving force. For example, the transmission member **1330** may include a bevel gear.

When the transmission member **1330** includes a worm gear, it is possible to prevent the cam member **1310** from being arbitrarily rotated by an external force.

The worm gear of the transmission member **1330** is arranged to extend in a direction perpendicular to the first direction X in which the rotating shaft **1313** of the cam member **1310** extends, and thus when the transmission member **1330** is arranged in the housing **1100**, a volume of the transmission member **1330** in the first direction X may be minimized. As described above, this is to maximize the volume of the washing chamber C in the first direction X.

The transmission member **1330** may connect the cam member **1310** and the driving motor **1320** to transfer the rotational force generated by the driving motor **1320** to the cam member **1310**, and at this time, the transmission member **1330** may be configured to allow the cam member **1310** to be rotated with an appropriate rotational speed. For example, the transmission member **1330** may be configured to reduce the rotational speed of the rotating shaft **1321** of the driving motor **1320**.

The transmission member 1330 may be configured in various ways according to design factors such as a target rotational speed of the cam member 1310 and a rotational speed of the driving motor 1320.

The automatic detergent dispenser 1000 may include a holder 1500 provided to allow the plurality of solid detergents to be maintained in the stacked state inside the storage compartment 1200 when the automatic detergent dispenser 1000 is disposed at the first position 1000A and the second position 1000B or during the automatic detergent dispenser 1000 is moved between the first position 1000A and the second position 1000B.

The holder 1500 may be moved in a direction, in which the long side 1201 of the storage compartment 1200 extends, by guides formed on the both side surfaces 1230 and 1240 of the storage compartment 1200.

In the storage compartment 1200, the holder 1500 may be provided to be movable toward the plurality of solid detergents in a direction in which the plurality of solid detergents is stacked. This is because the direction, in which the plurality of solid detergents is stacked, corresponds to the direction in which the long side 1201 of the storage compartment 1200 extends.

The holder 1500 may be disposed above the plurality of solid detergents in the storage compartment 1200 when the automatic detergent dispenser 1000 is disposed at the first position 1000A.

The holder 1500 may be movable from the upper side to the lower side of the storage compartment 1200 when the automatic detergent dispenser 1000 is disposed at the first position 1000A. The holder 1500 may be moved downward inside the storage compartment 1200 by gravity when the automatic detergent dispenser 1000 is disposed at the first position 1000A.

When the automatic detergent dispenser 1000 is disposed at the first position 1000A, the stacking direction of the plurality of solid detergents may correspond to the third direction Z, and the holder 1500 may be moved in the third direction Z by gravity. Accordingly, the holder 1500 may be provided to press the solid detergent, which is disposed at the highest position in the third direction Z among the plurality of solid detergents, downward.

The holder 1500 may include a weight member having a weight greater than a predetermined weight so as to be moved in the third direction Z by gravity. For example, the weight member may be integrally provided with the holder 1500. Alternatively, the weight member may be provided to be coupled to the holder 1500.

For example, the holder 1500 may be formed of a heavy material so as to have a weight greater than a predetermined weight.

The holder 1500 may be provided to have a weight greater than or equal to a predetermined weight and may be provided to press the plurality of solid detergents downward with respect to the third direction Z.

When the solid detergent, which is located at the lowest position in the third direction Z among the plurality of solid detergents, is discharged to the outside of the storage compartment 1200 by the ejector 1300, the plurality of solid detergents may be moved downward by gravity in the third direction Z corresponding to the stacking direction. The holder 1500 may press the plurality of solid detergents downward by gravity, and the holder 1500 may guide the downward movement of the plurality of solid detergents.

For example, when one of the plurality of solid detergents stacked in the third direction Z is separated from the arrangement and accordingly, some of the solid detergents

are supported on the both side surfaces 1230 and 1240 of the storage compartment 1200, the downward movement of the plurality of solid detergents may be limited. In this case, the holder 1500 may guide the downward movement of the plurality of solid detergents by pressing the plurality of solid detergents downward.

As described above, the automatic detergent dispenser 1000 may be provided to allow a plurality of solid detergents to be stacked in the third direction Z when the automatic detergent dispenser 1000 is disposed at the first position 1000A, and thus it is possible to increase the space efficiency of the automatic detergent dispenser 1000 and the dishwasher 1 in the first direction X and the second direction Y.

In addition, the automatic detergent dispenser 1000 may be provided to allow the plurality of solid detergents to be easily and sequentially discharged from the bottom in the direction of gravity as the plurality of solid detergents is disposed in the direction of gravity.

However, when the door 20 is rotated from the first position 20A to the second position 20B to open the tub 12 or disposed at the second position 20B, the direction in which the plurality of solid detergents is stacked may be arranged to be directed to a direction different from the third direction Z.

At this time, because the stacking direction of the plurality of solid detergents is directed to a direction different from the direction of gravity, one of the plurality of solid detergents may be separated from the stacked structure, and the stacked arrangement of the plurality of solid detergents in the third direction Z may be broken.

For example, as described above, the solid detergent D may be loaded into the storage compartment 1200 in such a way that one surface of the solid detergent D, which is formed in the horizontal length d1 and vertical length d2 directions, faces the cross-sectional area S of the storage compartment 1200 formed in the first direction X and the second direction Y.

For example, the surface of the solid detergent D formed in the horizontal length d1 and vertical length d2 directions may be provided in a curved surface rather than a flat surface. Accordingly, when the plurality of solid detergents D is stacked, the plurality of solid detergents, which face to each other in the stacking direction, may be arranged to allow curved faces thereof to face each other, and thus when the stacking direction of the plurality of solid detergents is directed to a direction different from the direction of gravity, the plurality of solid detergents may be separated from the stacked arrangement.

That is, when the plurality of solid detergents D is stacked to allow the curved surface thereof to face each other, it is more difficult to maintain the stacked state. Accordingly, when the stacking direction corresponds to the gravity direction, the holder 1500 may press the plurality of solid

detergents D to the stacking direction, and when the stacking direction is different from the gravity direction, the holder 1500 may support the plurality of solid detergents D so as to maintain the arrangement of the plurality of solid detergents D.

Even when the door 20 is disposed at the first position 20A again in a state in which the stacked arrangement of the plurality of solid detergents is broken, the movement of the plurality of solid detergents in the direction of gravity may be restricted. Further, the solid detergent, which is disposed at the lowest position in the third direction Z among the plurality of solid detergents, may be abnormally seated on the lower surface 1220 of the storage compartment 1200,

and thus the solid detergent may not be discharged to the outside of the storage compartment **1200** by the ejector **1300**.

That the solid detergent is abnormally seated on the lower surface **1220** means a state in which, when the solid detergent is placed on the lower surface **1220**, the ejector **1300** fails to press the solid detergent or means that the solid detergent is placed at a position in which the solid detergent is prevented from being discharged to the outside of the storage compartment **1200** even when the solid detergent is pressed by the ejector **1300**.

To prevent this, the holder **1500** may prevent the stacked arrangement of the plurality of solid detergents from being broken when the stacking direction of the plurality of solid detergents is directed to a direction different from the third direction **Z** due to the movement of the door **20**.

The holder **1500** may be provided to maintain the stacked arrangement of the plurality of solid detergents while the door **20** is moved from the first position **20A** to the second position **20B**, or even when the door **20** is disposed at the second position **20B**.

When the stacking direction of the plurality of solid detergents is directed to a direction different from the third direction **Z**, the holder **1500** may be provided to support the solid detergent disposed at the highest position in the third direction **Z** among the plurality of solid detergents.

When the stacking direction of the plurality of solid detergents is directed to a direction different from the third direction **Z**, the holder **1500** may be provided to be fixed at a position adjacent to the solid detergent disposed at the highest position in the third direction **Z** among the plurality of solid detergents.

When the stacking direction of the plurality of solid detergents is directed to a direction different from the third direction **Z**, the movement of the solid detergent, which is disposed at the highest position in the third direction **Z** among the plurality of solid detergents, may be blocked by the temporarily fixed holder **1500**, and thus it is possible to prevent the solid detergent, which is disposed at the highest position in the third direction **Z** among the plurality of solid detergents, from being separated from the stacked arrangement.

The storage compartment **1200** may include a guide rail **1290** provided to guide the movement of the holder **1500** inside the storage compartment **1200**.

The holder **1500** may be guided by the guide rail **1290** and translated in the extension direction of the long side **1201** of the storage compartment **1200**.

The guide rail **1290** may be provided to allow the holder **1500** to be moved downward in the third direction **Z** when the automatic detergent dispenser **1000** is disposed at the first position **1000A**.

For example, the holder **1500** may include a guide protrusion inserted into the guide rail **1290**. The guide protrusion of the holder **1500** may be inserted into the guide rail **1290** and moved along the extension direction of the guide rail **1290**.

The guide rail **1290** may be provided to extend in the extension direction of the long side **1201** of the storage compartment **1200**. The holder **1500** may be configured to be moved along the extension direction of the guide rail **1290**.

The guide rail **1290** may include a stopper **1293** provided to limit the movement of the holder **1500** when the automatic detergent dispenser **1000** is not positioned at the first position **1000A**.

While the door **20** is moved from the first position **20A** to the second position **20B**, the movement of the holder **1500** may be limited in the storage compartment **1200** as the movement of the guide protrusion of the holder **1500** is limited by the stopper **1293**.

Further, the holder **1500** may be provided to maintain the stacked arrangement of the plurality of solid detergents even when the door **20** is disposed at the second position **20B**.

When the stacking direction of the plurality of solid detergents is directed to a direction different from the third direction **Z**, the holder **1500** may be provided to support the solid detergent disposed at the highest position in the third direction **Z** among the plurality of solid detergents.

When the stacking direction of the plurality of solid detergents is directed to a direction different from the third direction **Z**, the holder **1500** may be provided to be fixed to a position adjacent to the solid detergent disposed at the highest position in the third direction **Z** among the plurality of solid detergents.

Accordingly, when the stacking direction of the plurality of solid detergents is directed to a direction different from the third direction **Z**, the holder **1500** may be temporarily fixed to the inside of the storage compartment **1200** by the stopper **1293**, and the movement of the solid detergent, which is disposed at the highest position in the third direction **Z** among the plurality of solid detergents, may be limited by the fixed holder **1500**.

Even when the stacking direction of the plurality of solid detergents is directed to a direction different from the third direction **Z**, the stacked arrangement of the plurality of solid detergents may be maintained by the holder **1500**. Accordingly, even when the plurality of solid detergents is stacked in the third direction **Z** in the state in which the automatic detergent dispenser **1000** is disposed at the first position **1000A**, the automatic detergent dispenser **1000** may be configured to allow one of the plurality of solid detergents to be discharged to the outside of the storage compartment **1200** and then input to the tub **12**.

The automatic detergent dispenser **1000** may include the seating member **1400** provided to seat one solid detergent discharged from the storage compartment **1200**.

The seating member **1400** may be provided to communicate with the storage compartment outlet **1210**. The seating member **1400** may include a seating member inner space **1401** provided to communicate with the storage compartment outlet **1210**.

One of the plurality of solid detergents may be discharged from the storage compartment **1200** through the storage compartment outlet **1210** and moved to the seating member inner space **1401**.

The seating member may include a discharge guide **1430** connected to the tub **12**. The discharge guide **1430** may be provided as a space connected to the seating member inner space **1401**.

For example, the seating member inner space **1401** and the discharge guide **1430** may be formed as one space, and the seating member inner space **1401** and the discharge guide **1430** may be partitioned by a seating member opening **1420** that is opened or closed by a seating member door **1410** described later.

For example, a lower end of the seating member inner space **1401** in the third direction **Z** may be formed as the seating member opening **1420**, and the discharge guide **1430** may be a region that is formed from the seating member opening **1420** to the lower side with respect to the third direction **Z**.

The seating member **1400** may be provided to allow one solid detergent, which is moved to the seating member inner space **1401**, to be temporarily seated on the seating member **1400** and then to be input into the tub **12**.

The seating member **1400** may include the seating member opening **1420** that is connected to the discharge guide **1430** through which the seating member inner space **1401** is connected to the tub **12**. The seating member opening **1420** may be provided to open toward the third direction Z when the automatic detergent dispenser **1000** is disposed at the first position **1000A**.

The seating member **1400** may include the seating member door **1410** configured to open and close the seating member opening **1420**. When the seating member door **1410** closes the seating member opening **1420**, the seating member door **1410** may be provided to form a lower surface of the seating member inner space **1401**.

The seating member door **1410** may include a seating surface **1411** on which the solid detergent is seated when the seating member door **1410** closes the seating member opening **1420**. The seating surface **1411** may be disposed to face upward in the third direction Z when the seating member door **1410** closes the seating member opening **1420**.

For example, the seating member opening **1420** may be defined as a surface closed by the seating member door **1410** in the seating member inner space **1401**. Accordingly, a region formed above the upper surface of the seating member opening **1420** may be defined as the seating member inner space **1401**, and a region formed below the lower surface of the seating member opening **1420** may be defined as the discharge guide **1430**. When the seating member door **1410** closes the seating member opening **1420**, the seating surface **1411** may be disposed on the seating member opening **1420**, and accordingly, the seating surface **1411** may be defined as the lower surface of the seating member inner space **1401**.

For example, the lower surface of the seating member inner space **1401** may be defined as the seating member opening **1420**, but when the seating member door **1410** closes the seating member opening **1420**, the lower surface of the seating member inner space **1401** may be defined as the seating member door **1410**.

The seating member door **1410** may be provided to seal the seating member inner space **1401** from the outside when the seating member door **1410** closes the seating member opening **1420**. Further, the seating member door **1410** may connect the seating member inner space **1401** and the tub **12** when the seating member door **1410** opens the seating member opening **1420**.

The seating member **1400** may include the seating member door driver **1470** configured to open and close the seating member door **1410**.

For example, the seating member door driver **1470** may include a driving motor and a transmission member.

For example, the transmission member of the seating member door driver **1470** may include a plurality of gears. For example, when the driving motor is rotated in one direction, the plurality of gears may transmit a rotational force in one direction to the seating member door **1410**. The seating member door **1410** may be rotated in one direction by the received rotational force, so as to open the seating member opening **1420** in a state in which the seating member door **1410** closes the seating member opening **1420**.

For example, when the driving motor is rotated in the opposite direction, the plurality of gears may transmit the rotational force in the opposite direction to the seating member door **1410**. The seating member door **1410** may be

rotated in the opposite direction by the received rotational force, so as to close the seating member opening **1420** in a state in which the seating member door **1410** opens the seating member opening **1420**.

5 The seating member opening **1420** may communicate with the inlet **1122** by the discharge guide **1430**. One solid detergent located in the seating member inner space **1401** may be discharged from the seating member inner space **1401** through the seating member opening **1420**, and then 10 discharged from the seating member opening **1420** to the outside of the automatic detergent dispenser **1000** through the inlet **1122**. Accordingly, the solid detergent may be input to the tub **12**.

The seating member **1400** may include the discharge 15 guide **1430** formed between the seating member opening **1420** and the inlet **1122** and provided to guide the movement in which the solid detergent is moved from the seating member opening **1420** to the inlet **1122**.

One solid detergent discharged from the storage compartment **1200** may be temporarily seated on the seating member **1400**, and particularly, the solid detergent may be located on the seating surface **1411** of the seating member door **1410** forming the lower surface of the seating member inner space **1401**.

25 The inlet **1122** may be opened and closed by the inlet cover **1150**. The inlet cover **1150** may open the inlet **1122** while the solid detergent discharged along the discharge guide **1430** presses the inlet cover **1150**.

The solid detergent may pass through the inlet **1120** while 30 pressing the inlet cover **1150**, and then move to the tub **12**.

When the seating member door **1410** opens the seating member opening **1420**, the solid detergent placed on the seating member door **1410** may be moved downward by gravity, and then discharged to the outside of the seating member inner space **1401** through the seating member opening **1420**.

35 The automatic detergent dispenser **1000** may be configured to allow one solid detergent, which is discharged from the storage compartment **1200**, to be moved to the outside of the storage compartment **1200** through the seating member **1400** without being immediately discharged to the outside of the automatic detergent dispenser **1000**.

The storage compartment **1200** may include an intermediate door **1250** configured to open and close the storage compartment outlet **1210**. The intermediate door **1250** may be configured to prevent a solid detergent, which is loaded into the storage compartment **1200**, from being moved to the seating member **1400** by an external force without being discharged from the storage compartment **1200** by the ejector **1300**.

45 The intermediate door **1250** may be biased in a direction to close the storage compartment outlet **1210**. The intermediate door **1250** may include an elastic member **1251**, and the intermediate door **1250** may be biased toward the storage compartment outlet **1210** by the elastic member **1251** to allow the intermediate door **1250** to close the storage compartment outlet **1210**.

50 The solid detergent, which is pressed by the ejector **1300** and moved to the storage compartment outlet **1210** among the plurality of solid detergents loaded into the storage compartment **1200**, may open the intermediate door **1250** by pressing the intermediate door **1250**. As the intermediate door **1250** is opened, the solid detergent may be moved to the seating member **1400** through the storage compartment outlet **1210**.

55 Even when the solid detergent is moved toward the storage compartment outlet **1210** by an external force, not by

the pressing of the ejector **1300**, the solid detergent may be blocked by the intermediate door **1250** and thus the solid detergent may not pass through the storage compartment outlet **1210** and may not be discharged from the storage compartment **1200**.

When the solid detergent is moved by the presser **1312a** and collides with the intermediate door **1250**, the ejector **1300** may press the solid detergent to allow the biased intermediate door **1250** to be opened by the pressing of the solid detergent.

A force by which the intermediate door **1250** closes the storage compartment outlet **1210** by the elastic member **1251** may be set to be less than a force by which the solid detergent presses the door **1250** by the pressing of the ejector **1300**.

As the seating member **1400** is formed between the storage compartment outlet **1210** and the tub **12**, the storage compartment outlet **1210** may be connected to the tub **12** through the seating member **1400** without being directly connected to the tub **12**.

When the storage compartment outlet **1210** is directly connected to the tub **12**, the water remaining in the tub **12** may flow into the storage compartment **1200** through the storage compartment outlet **1210**, and thus the plurality of solid detergents loaded inside the storage compartment **1200** may be damaged or deformed by the water.

In order to prevent this, the storage compartment outlet **1210** may be provided to be bypassed to the tub **12** through the seating member **1400** without being directly connected to the tub **12**.

When it is required to input the solid detergent to the tub **12**, the seating member **1400** may open the seating member opening **1420** to allow the seating member inner space **1401** to communicate with the tub **12**. The seating member door **1410** may close the seating member opening **1420** at a stage when the solid detergent is not input into the tub **12**, so as to minimize a flow of water, which remains in the tub **12**, into the seating member inner space **1401**.

The seating member **1400** may include a seating member sensor **1440** configured to detect whether a solid detergent is seated on the seating member **1400**.

Because the storage compartment **1200** is provided to communicate with the seating member **1400**, it is inevitable that the seating member sensor **1440** detects whether the solid detergent discharged from the storage compartment **1200** is seated on the seating member **1400**.

The seating member sensor **1440** may be provided as a position sensor. For example, the seating member sensor **1440** may include an optical sensor.

The seating member sensor **1440** may detect whether or not the solid detergent is located in the seating member **1400**, and the control device **1900** (refer to FIG. 5) of the dishwasher **1** may control the automatic detergent dispenser **1000** based on a value detected by the seating member sensor **1440**.

The control device **1900** may receive information related to whether the solid detergent is loaded in the storage compartment **1200**, whether the solid detergent is seated on the seating member **1400** after the ejector **1300** is driven in a state in which the solid detergent is loaded in the storage compartment **1200**, and whether the solid detergent is discharged from the seating member **1400** after the solid detergent is seated on the seating member **1400**, and control the automatic detergent dispenser **1000** based on the received information.

The control device **1900** may be configured to communicate with the main control device of the dishwasher **1** and

configured to allow the controller to control the dishwasher **1** based on the received information.

For example, the control device **1900** and the main control device may be subordinate components of the controller, and both the dishwasher **1** and the automatic detergent dispenser **1000** may be controlled by the controller. However, in the following description, it is assumed that the automatic detergent dispenser **1000** is controlled by the control device **1900** only for the control of the automatic detergent dispenser **1000**.

For example, when the seating member sensor **1440** fails to detect the solid detergent after the ejector **1300** is driven, the control device **1900** may determine that the solid detergent is not discharged from the storage compartment **1200** because the solid detergent is not loaded into the storage compartment **1200**, or determine that the solid detergent is not discharged from the storage compartment **1200** due to a malfunction of the ejector **1300** even when the solid detergent is loaded into the storage compartment **1200**. Based on the determination, the control device **1900** may control the automatic detergent dispenser **1000**.

For example, the control device **1900** may allow the ejector **1300** to be driven again to move the solid detergent to the seating member **1400**. In addition, the control device **1900** may communicate with the main control device, and the controller may control the dishwasher **1** not to perform the washing process of the dishwasher **1** based on a communication value.

For example, when the seating member sensor **1440** continuously fails to detect the solid detergent after the control device **1900** controls the ejector **1300** to be driven again, the control device **1900** may communicate with the main control device, and the controller may control the dishwasher **1** not to perform the washing process of the dishwasher **1** based on a communication value. Further, the controller may control a display to inform a user that there is no solid detergent in the storage compartment **1200**.

For example, the display may be implemented as a display positioned on the main body **10** of the dishwasher **1**. For example, the display may be implemented in a separate device configured to communicate with the dishwasher **1**.

For example, when the seating member sensor **1440** fails to detect the solid detergent after the detection state is maintained since the seating member sensor **1440** detects the solid detergent in the seating member, the control device **1900** may determine that the solid detergent is discharged from the seating member **1400** and then input to the tub **12**, and the control device **1900** may control the automatic detergent dispenser **1000** based on the determination. For example, the control device **1900** may communicate with the main control device, and the controller may control the dishwasher **1** to perform the washing process of the dishwasher **1** based on the communication value.

As the seating member sensor **1440** senses the position of the solid detergent in the seating member **1400**, the control device **1900** may be configured to identify all of the above situations, and thus it is possible to minimize the number of additional sensors configured to detect a position of a solid detergent. That is, even when a position sensor, which is configured to additionally detect a position of the solid detergent, is not placed to the storage compartment **1200** or the discharge guide **1430**, the control device **1900** may be configured to determine all of whether the solid detergent is located in the storage compartment **1200**, or whether the solid detergent is located in the seating member inner space **1401** or whether the solid detergent is located in the outside

of the seating member 1400, by placing the seating member sensor 1440 on the seating member 1400. This will be described later in detail.

As described above, the storage compartment 1200 may be provided in plurality. For example, two storage compartments 1200 may be provided.

Hereinafter for convenience of description, the storage compartment 1200 disposed on the left side in the second direction Y with respect to FIG. 8 is defined as a first storage compartment 1200, and a storage compartment 1200' disposed on the right side is defined as a second storage compartment 1200'. In addition, a configuration of the first storage compartment 1200 is defined as a first configuration, and a configuration of the second storage compartment 1200' is defined as a second configuration. For example, the intermediate door 1250 of the first storage compartment 1200 is defined as a first intermediate door 1250 and an intermediate door 1250' of the second storage compartment 1200' is defined as a second intermediate door 1250'.

In addition, an ejector configured to discharge a solid detergent stored in the first storage compartment 1200 is defined as a first ejector 1300, and an ejector configured to discharge a solid detergent stored in the second storage compartment 1200' is defined as a second ejector 1300'. In addition, a holder 1500 disposed inside the first storage compartment 1200 is defined as a first holder 1500, and a holder 1500 disposed inside the second storage compartment 1200' is defined as a second holder 1500'.

The first and second storage compartments 1200 and 1200' may be provided to be spaced apart from each other in the second direction Y. The first and second storage compartments 1200 and 1200' include long sides extending in the third direction Z when the automatic detergent dispenser 1000 is disposed at the first position 1000A, respectively. Accordingly, when the first and second storage compartments 1200 and 1200' are provided to be spaced apart from each other in the second direction Y, the first and second storage compartments 1200 and 1200' may be efficiently arranged inside the automatic detergent dispenser 1000.

Due to the first and second storage compartments 1200 and 1200', a user can load a large number of solid detergents into the automatic detergent dispenser 1000 at one time.

The seating member 1400 may be disposed between the first storage compartment 1200 and the second storage compartment 1200' in the second direction Y. The first storage compartment 1200 may be provided to communicate with the seating member 1400 as described above, and the second storage compartment 1200' may also be provided to communicate with the seating member 1400.

Accordingly, the first and second storage compartments 1200 and 1200' may communicate with the tub 12 through a single seating member 1400 arranged between the first storage compartment 1200 and the second storage compartment 1200' in the second direction Y.

This is to minimize the expansion of the automatic detergent dispenser 1000 in the second direction Y as the first and second storage compartments 1200 and 1200' share the seating member 1400. That is, when a plurality of seating members 1400 is provided to correspond to the first and second storage compartments 1200 and 1200', the automatic detergent dispenser 1000 may increase in volume in the second direction Y due to the plurality of seating members. However, as for the automatic detergent dispenser 1000, the first and second storage compartments 1200 and 1200' may communicate with each other through a single seating member 1400 as described above, and thus it is possible to

minimize the length of the automatic detergent dispenser 1000 in the second direction Y.

Based on FIG. 8, the first storage compartment 1200 may be disposed on the left side of the seating member 1400, and the second storage compartment 1200' may be disposed on the right side of the seating member 1400 with respect to the second direction Y.

As described above, while the first cam member 1310 is rotated clockwise, the first cam member 1310 may move a solid detergent seated on the first lower surface 1220 of the first storage compartment 1200 to the right side of the first storage compartment 1200, and as the first storage compartment outlet 1210 is disposed below the first right surface 1230 of the first storage compartment 1200, the solid detergent may be moved to the seating member 1400 disposed on the right side of the first storage compartment 1200.

The first cam member 1310 may be provided to be rotated in a clockwise direction by interlocking with the first driving motor 1320 and the first transmission member 1330.

Conversely, a second cam member 1310' may be rotated counterclockwise. Unlike the first ejector 1300, the second ejector 1300' may be configured to move the solid detergent loaded in the second storage compartment 1200' to the left side.

The second cam member 1310' may be configured to be rotated in a counterclockwise direction by interlocking with a second driving motor 1320' and a second transmission member 1330'.

While the second cam member 1310' is rotated counterclockwise, the second cam member 1310' may move a solid detergent seated on a second lower surface 1220' of the second storage compartment 1200' to the left side of the second storage compartment 1200', and as a second storage compartment outlet 1210' is disposed below the second left surface 1240' of the second storage compartment 1200', the solid detergent may be moved to the seating member 1400 disposed on the left side of the second storage compartment 1200'.

The second storage compartment 1200' may include a second penetration member 1221' formed on the second lower surface 1220' of the second storage compartment 1200' and provided to allow a second presser 1312a' to be moved from the outside of the second storage compartment 1200' to the inside of the second storage compartment 1200'.

The second penetration member 1221' may be provided to extend not only to the second lower surface 1220' of the second storage compartment 1200' but also to the lower side of a second right surface 1230' and a second left surface 1240' of the second storage compartment 1200'.

The second presser 1312a' may be rotated by the rotation of the second cam member 1310' and moved into the second storage compartment 1200' through the lower side of the second right surface 1230' and the second penetration member 1221' of the second lower surface 1220', and then moved to the outside of the second storage compartment 1200' through the lower side of the second left surface 1240' and the second penetration member 1221' of the second lower surface 1220'.

The second presser 1312a' may be provided to be rotated while pressing the solid detergent seated on the second lower surface 1220', so as to allow the solid detergent to be moved to the left side.

The first rotating shaft 1313 of the first cam member 1310 may be disposed between the first left surface 1240 and the first right surface 1230 of the first storage compartment 1200 in the second direction Y. For example, the first rotating shaft 1313 of the first cam member 1310 may be disposed at the

center of the left surface 1240 and the right surface 1230 of the first storage compartment 1200 in the second direction Y.

A second rotating shaft 1313' of the second cam member 1310' may be disposed between the second left surface 1240' and the second right surface 1230' of the second storage compartment 1200' in the second direction Y. For example, the second rotating shaft 1313' of the second cam member 1310' may be disposed at the center of the second left surface 1240' and the second right surface 1230' of the second storage compartment 1200' in the second direction Y.

A reason why the first and second rotating shafts 1313 and 1313' of the first and second cam members 1310 and 1310' are respectively at the center of the first and second storage compartments 1200 and 1200' disposed in the second direction Y as mentioned above, is to stably support and press the solid detergent when the first and second pressers 1312a and 1312a' of the first and second cam members 1310 and 1310' are rotated.

When the first and second rotating shafts 1313 and 1313' of the first and second cam members 1310 and 1310' are disposed outside the center of the first and second storage compartments 1200 and 1200' in the second direction Y, the first and second pressers 1312a and 1312a' may pass through the first and second penetration members 1221 and 1221' with a predetermined length or less of the first and second pressers 1312a and 1312a' and thus it is difficult for the first and second pressers 1312a and 1312a' to stably support the solid detergent, in a section in which the first and second pressers 1312a and 1312a' pass through the first and second penetration members 1221 and 1221' by the rotation of the first and second cam members 1310 and 1310'.

In a section in which the first and second pressers 1312a and 1312a' enter or exit the first and second storage compartments 1200 and 1200' by passing through the first and second penetration members 1221 and 1221', the first and second pressers 1312a and 1312a' may pass through the first and second penetration members 1221 and 1221' with a predetermined length or less of the first and second pressers 1312a and 1312a' and thus it is difficult for the first and second pressers 1312a and 1312a' to stably support the solid detergent loaded into the first and second storage compartments 1200 and 1200'.

To prevent this, the first and second rotating shafts 1313 and 1313' of the first and second cam members 1310 and 1310' may be respectively disposed at the center of the first and second storage compartments 1200 and 1200' in the second direction Y in order that the first and second pressers 1312a and 1312a' pass through the first and second penetration members 1221 and 1221' and are rotated with a predetermined length or more of the first and second pressers 1312a and 1312a', in a section in which the first and second pressers 1312a and 1312a' enter or exit the first and second storage compartments 1200 and 1200' through the first and second penetration members 1221 and 1221'.

When the first and second rotating shafts 1313 and 1313' of the first and second cam members 1310 and 1310' are not respectively disposed at the center of the first and second storage compartments 1200 and 1200' in the second direction Y, the volume of the automatic detergent dispenser 1000 in the second direction Y may increase. Accordingly, it is appropriate that the first and second rotating shafts 1313 and 1313' of the first and second cam members 1310 and 1310' are respectively disposed at the center of the first and second storage compartments 1200 and 1200' in the second direction Y.

The first ejector 1300 and the second ejector 1300' may be provided to be driven in a mirror-symmetrical direction in

the second direction Y with respect to the seating member 1400. The first cam member 1310 and the second cam member 1310' may be configured to be rotated in opposite directions to each other so as to be mirror symmetrical about the seating member 1400.

In order that the first storage compartment 1200 and the second storage compartment 1200' are disposed on opposite sides of the seating member 1400 with respect to the second direction Y and the solid detergent discharged from the first 10 and second storage compartments 1200 and 1200' is moved to the seating member 1400, the first ejector 1300 and the second ejector 1300' may be provided to be driven in a mirror-symmetrical direction Y with respect to the seating member 1400 in the second direction Y.

15 A width L1 of the first storage compartment 1200 in the second direction Y (or referred to as the horizontal length) may be substantially the same as a width L1 of the second storage compartment 1200'.

The width L1 of the first and second storage compartments 20 1200 and 1200' in the second direction Y may substantially correspond to a width L3 of the seating member 1400. When the solid detergent is discharged from the first and second storage compartments 1200 and 1200' in a state in which the width L3 of the seating member 1400 in 25 the second direction Y is excessively less than the width L1 of the first and second storage compartments 1200 and 1200', the solid detergent may be stuck in the seating member inner space 1401 without being seated on the seating member door 1410.

30 Conversely, when the width L3 of the seating member 1400 in the second direction Y is excessively greater than the width L1 of the first and second storage compartments 1200 and 1200', the volume of the seating member 1400 in the second direction Y may increase more than necessary and 35 thus the volume of the automatic detergent dispenser 1000 in the second direction Y may increase more than necessary.

Therefore, as described above, it is appropriate that the width L3 of the seating member 1400 may have a length corresponding to the width L1 of the first and second storage 40 compartments 1200 and 1200' having a cross-sectional area S in accordance with the size of the solid detergent, in the second direction Y.

Hereinafter the operation of the automatic detergent dispenser 1000 will be described in detail.

45 FIG. 8 is a view illustrating a state in which some components of the automatic detergent dispenser of the dishwasher according to an embodiment are removed, FIG. 9 is a view illustrating a state in which a solid detergent loaded in a first storage compartment is discharged from the first storage compartment of FIG. 8, FIG. 10 is a view illustrating a state in which the solid detergent of FIG. 9 is seated on a seating member, FIG. 11 is a view illustrating a state in which the solid detergent of FIG. 10 is discharged from the automatic detergent dispenser, and FIG. 12 is a 50 view illustrating a state in which a solid detergent loaded in a second storage compartment is discharged from the second storage compartment of FIG. 8.

55 As shown in FIGS. 8 and 9, the control device 1900 may control the first ejector 1300 or the second ejector 1300' to allow one of the plurality of solid detergents stacked in one of the first storage compartment 1200 and the second storage compartment 1200' to be moved to the seating member 1400.

60 For example, the control device 1900 may control the first ejector 1300 to be driven. The control device 1900 may control the first ejector 1300 to be driven again or control the second ejector 1300' to be driven based on the sensing value

of the seating member sensor 1440. A description thereof will be described later in detail.

By driving the first driving motor 1320, the control device 1900 may control the first ejector 1300 to allow the first cam member 1310 to be rotated clockwise.

By driving the second driving motor 1320', the control device 1900 may control the second ejector 1300' to allow the second cam member 1310' to be rotated clockwise.

The control device 1900 may control the position of the first cam member 1310 to allow the first cam region 1310A1 of the first cam member 1310 to be arranged at the upper end in the third direction Z before the first cam member 1310 is rotated and the first presser 1312a is moved into the storage compartment 1200.

When the first cam region 1310A1 of the first cam member 1310 is arranged at the upper end of the first cam member 1310 in the third direction Z, the first cam region 1310A1 may be disposed below the first support surface 1222 of the storage compartment 1200 in the third direction Z as described above. Accordingly, the solid detergent located at the lowest position in the third direction Z among the plurality of solid detergents loaded in the first storage compartment 1200 may be stably seated on the first support surface 1222, and thus the first presser 1312a may stably move the solid detergent to the second direction Y by the rotation of the first cam member 1310.

For example, when a part of the first cam member 1310 protrudes higher than the first support surface 1222 in the third direction Z through the first penetration member 1221, the solid detergent located at the lowest position in the third direction Z among the plurality of solid detergents loaded in the first storage compartment 1200 may not be horizontally disposed in the third direction Z. Accordingly, when the solid detergent is moved in the second direction Y, the solid detergent may be rotated or moved to another direction without being moved to the second direction Y by the center of gravity. Accordingly, the solid detergent may not be moved toward the first storage compartment outlet 1210 and may not be discharged to the outside of the first storage compartment 1200.

Accordingly, the control device 1900 may control the position of the first cam member 1310 to allow the first cam region 1310A1 of the first cam member 1310 to be arranged at the upper end in the third direction Z when the dishwasher 1 does not perform the washing process. Thereafter, when the dishwasher 1 performs the washing process, the control device 1900 may communicate with the main control device and the control device 1900 may control the first ejector 1300 to allow the first cam member 1310 to be rotated clockwise based on a communication value.

The first presser 1312a may be interlocked with the rotation of the first cam member 1310 and moved into the first storage compartment 1200, and accordingly, the solid detergent located at the lowest position in the third direction Z may be moved to the right side with respect to the second direction Y by the first presser 1312a.

The solid detergent may be pressed by the first presser 1312a and moved to the first storage compartment outlet 1210, and while the solid detergent opens the first intermediate door 1250 provided to close the first storage compartment outlet 1210, the solid detergent may be discharged to the outside of the first storage compartment 1200 through the first storage compartment outlet 1210.

Thereafter, the solid detergent may be disposed on the seating member 1400, particularly, on the seating member door 1410, as illustrated in FIG. 10.

The seating member sensor 1440 may detect the position of the solid detergent, that is, whether or not the solid detergent is located in the seating member inner space 1401. Particularly, the seating member sensor 1440 may be arranged on the seating member door 1410 in the third direction Z and configured to detect whether the solid detergent is located on the seating member door 1410.

The control device 1900 may receive information on the position of the solid detergent located on the seating member door 1410 by the seating member sensor 1440 and communicate with the main control device, and the controller may control the dishwasher 1 to allow the dishwasher 1 to perform the washing process based on the communicated value.

For example, the washing process of the dishwasher 1 may be divided into the pre-washing operation, the main washing operation, the rinsing operation, and the drying operation. The controller may control the dishwasher 1 to allow the dishwasher 1 to perform the pre-washing operation based on the communicated value.

For example, when the seating member sensor 1440 fails to detect the solid detergent after driving the first ejector 1300 once, the control device 1900 may transmit the information that no solid detergent is detected to the main control device. The controller may control the dishwasher 1 to allow the dishwasher 1 not to perform the pre-washing operation of the washing process based on the communicated value. This is because, in some cases, a user can open the door 20 to load the solid detergent into the automatic detergent dispenser 1000. Accordingly, the controller may control the dishwasher 1 not to start the washing process itself when no solid detergent is placed in the seating member 1400.

For example, when the seating member sensor 1440 fails to detect the solid detergent after driving the first ejector 1300 once, the control device 1900 may additionally drive the first ejector 1300 once again, which is different from FIG. 10. As described above, the controller may control the dishwasher 1 to allow the dishwasher 1 not to perform the washing process.

This is to drive the first ejector 1300 again to move the solid detergent to the second direction Y by the first presser 1312a so as to allow the solid detergent to be discharged to the outside of the first storage compartment 1200 when the solid detergent, which is disposed at the lowest position in the third direction Z among the plurality of solid detergents loaded into the first storage compartment 1200, is not stably seated on the first support surface 1222 and moved to another direction without being moved to the second direction Y by the first presser 1312a and thus the solid detergent is not discharged to the first storage compartment outlet 1210.

Thereafter, the control device 1900 may receive information on the position of the solid detergent located on the seating member door 1410 by the seating member sensor 1440 and communicate with the main control device, and the controller may control the dishwasher 1 to allow the dishwasher 1 to perform the washing process based on the communicated value.

As illustrated in FIG. 11, when the dishwasher 1 performs the main washing operation of the washing process by the controller, the control device 1900 may open the seating member door 1410 to allow the solid detergent to be discharged from the seating member inner space 1401 and to be input to the tub 12 through the discharge guide 1430.

When the seating member door 1410 opens the seating member opening 1420, the solid detergent may be moved to the discharge guide 1430 through the seating member open-

ing 1420, and the solid detergent may be discharged from the automatic detergent dispenser 1000 along the discharge guide 1430 through the inlet 1122.

For example, the seating member door 1410 may open the seating member opening 1420 while rotating downward, and the solid detergent placed on the seating member door 1410 may be moved to the discharge guide 1430 by passing through the seating member opening 1420 while the solid detergent is moved downward according to the rotation of the seating member door 1410.

The control device 1900 may rotate the seating member door 1410 to allow the seating member door 1410 to open the seating member opening 1420, and after a predetermined time elapses, the control device 1900 may rotate the seating member door 1410 to the opposite direction to allow the seating member door 1410 to close the seating member opening 1420, again.

This is because while the seating member opening 1420 is opened for a predetermined period of time, water may flow from the tub 12 into the storage compartment 1200 through the seating member 1400. To prevent this, the control device 1900 may control opening and closing of the seating member door 1410.

The control device 1900 may control the seating member door driver 1470 to open and close the seating member door 1410. The seating member door driver 1470 may transmit a rotational force, which is in one direction or the opposite direction, to the seating member door 1410 under the control of the control device 1900, so as to drive the seating member door 1410 to open and close the seating member opening 1420.

When the control device 1900 receives information that no solid detergent is located in the seating member 1400 from the seating member sensor 1440 after the control device 1900 controls the seating member door 1410 to be opened and closed, the control device 1900 may communicate with the main control device and the controller may control the dishwasher 1 to perform the main washing operation of the washing process based on the communicated value.

This is to prevent the dishwasher 1 from performing the main washing operation in a state in which the solid detergent is not discharged from the seating member inner space 1401 due to adhesion of the solid detergent to the seating member door 1410 even when the seating member door 1410 opens and closes the seating member opening 1420.

The control device 1900 may receive information that no solid detergent is located in the seating member 1400 from the seating member sensor 1440 after the control device 1900 controls the seating member door 1410 to be opened and closed, and the control device 1900 may control the position of the first cam member 1310 to allow the first cam region 1310A1 of the cam member 1310 to be disposed at the upper end in the third direction Z.

Accordingly, as the solid detergent located at the lowest position in the third direction Z among the plurality of solid detergents is discharged to the outside of the first storage compartment 1200, the plurality of solid detergents loaded in the first storage compartment 1200 may be moved downward and a solid detergent, which is positioned directly above the discharged solid detergent, may be stably placed on the support surface 1222.

By repeating the above-described process, the control device 1900 may control the automatic detergent dispenser 1000 to allow the solid detergent to be automatically input into the tub 12 in response to the dishwasher 1 performing the washing process.

When receiving information that no solid detergent is detected by the seating member sensor 1440 after driving the first ejector 1300, the control device 1900 may drive the first ejector 1300 one more time and receive information on whether or not the solid detergent is detected from the seating member sensor 1440, as described above.

When receiving information that no solid detergent is detected by the seating member sensor 1440 even after driving the first ejector 1300 one more time, the control device 1900 may drive the second ejector 1300' based on the information.

Because all of the plurality of solid detergents loaded in the first storage compartment 1200 is discharged from the first storage compartment 1200, the seating member sensor 1440 may fail to detect the solid detergent even after the control device 1900 controls the first ejector 1300 to be driven twice.

Accordingly, the control device 1900 may control the second ejector 1300' to be driven. The feature of driving the second ejector 1300' by the control device 1900 is the same as the feature of driving the first ejector 1300 by the control device 1900, and thus a description thereof will be omitted.

As illustrated in FIGS. 10 and 11, as the presser 1312a presses the solid detergent located at the lowest position among the plurality of solid detergents according to the rotation of the cam member 1310 and as the presser 1312a is moved out of the storage compartment 1200, the plurality of solid detergents in the stacked state may be moved downward with respect to the third direction Z.

The cam member 1310 may be provided to guide the plurality of solid detergents loaded and stacked inside the storage compartment 1200 to be moved in parallel to the third direction Z. Particularly, the cam member 1310 may be provided to guide the plurality of solid detergents seated on the rim of the cam member 1310 to gradually descend in the storage compartment according to the rotation of the cam member 1310.

In the above description, the configuration and operation of the automatic detergent dispenser 1000 of the dishwasher 1 according to an embodiment of the disclosure have been described with reference to FIGS. 1 to 12. However, the disclosure is not limited thereto, and the contents described above are merely examples of the dishwasher and the automatic detergent dispenser according to the disclosure.

For example, when the automatic detergent dispenser 1000 is at the first position 1000A, the plurality of solid detergents may be stacked and loaded in a direction different from the third direction Z that is a direction different from the vertical direction of the dishwasher 1, in the storage compartment 1200.

For example, when the automatic detergent dispenser 1000 is at the first position 1000A, the automatic detergent dispenser 1000 may include a storage compartment including a long side extending in the second direction Y, which is the left and right direction of the dishwasher 1. A plurality of solid detergents may be stacked and loaded in the second direction Y inside the storage compartment. The automatic detergent dispenser 1000 may include a holder configured to move the plurality of solid detergents, which is stacked in the second direction Y inside the storage compartment, to the second direction Y. For example, the holder may include an elastic member, and thus the holder may move the plurality of solid detergents to the second direction Y toward a cam member of an ejector. The cam member may press one of the plurality of solid detergents to be discharged to the outside of the storage compartment. For example, the solid detergent may be discharged to a direction perpendicular to

the second direction Y and then moved to the lower side of the storage compartment. One solid detergent discharged to the outside of the storage compartment may be introduced into the tub 12 through a seating member or the like.

As an example, when the automatic detergent dispenser 1000 is at the first position 1000A, the automatic detergent dispenser 1000 may include storage compartments 1200 and 1200' in which a plurality of solid detergents is stacked and loaded in the third direction Z, as illustrated in FIGS. 1 to 12. However, unlike those shown in FIGS. 1 to 12, the automatic detergent dispenser 1000 may be provided to allow a plurality of solid detergents to be moved upward in the storage compartments 1200 and 1200' and then discharged. The automatic detergent dispenser 1000 may include a holder arranged inside the storage compartments 1200 and 1200' and configured to move the plurality of solid detergents to the upper side. For example, the holder may include an elastic member, and thus the holder may move the plurality of solid detergents to the upper side. A cam of an ejector may be disposed above the storage compartments 1200 and 1200', and one solid detergent disposed at the highest position among the plurality of solid detergents may be moved out of the storage compartment 1200 by the cam of the ejector. One solid detergent moved to the outside of the storage compartment 1200 may be introduced into the tub 12 through a seating member or the like.

It is illustrated that when the automatic detergent dispenser 1000 is at the first position 1000A, the plurality of solid detergents is stacked and loaded in the third direction Z, which is the vertical direction, inside the storage compartments 1200 and 1200'. The term "third direction", which refers to the direction in which the plurality of solid detergents is stacked and loaded inside the storage compartments 1200 and 1200', is only a term for defining the stacking direction of the plurality of solid detergents. Therefore, the stacking direction of the plurality of solid detergents is not limited by the term "third direction". For example, the stacking direction of the plurality of solid detergents may be referred to as a "first direction" as needed, and even in this case, the term "first direction" may represent the Z direction shown in the drawings according to an embodiment of the disclosure (it is assumed that the automatic detergent dispenser 1000 is at the first position 1000A) and the like. Hereinafter the holder 1500 will be described in detail. Hereinafter, a cross-sectional area of the storage compartment 1200 according to an example will be described in detail.

FIG. 13 is a view illustrating a state in which some components of the automatic detergent dispenser of the dishwasher according to an embodiment are removed.

For example, as shown in FIG. 13, the horizontal length L1 of the first storage compartment 1200 and a horizontal length L5 of the second storage compartment 1200' may be different from each other.

For example, the horizontal length L1 of the first storage compartment 1200 may be provided to have a predetermined length to allow the above-described solid detergent D to be stored in the storage compartment 1200. The horizontal length L5 of the second storage compartment 1200' may be less than the horizontal length L1 of the first storage compartment 1200.

For example, the horizontal length L5 of the second storage compartment 1200' may be greater than the horizontal length L1 of the first storage compartment 1200.

The width L4 of the seating member 1400 in the second direction Y may be substantially similar to the width L1 of the first storage compartment 1200. This is because, when

the solid detergent is discharged from the first storage compartment 1200 to the seating member 1400 in a state in which the width L4 of the seating member 1400 is excessively less than the width L5 of the second storage compartment 1200', the solid detergent may be stuck in the seating member inner space 1401 without being seated on the seating member door 1410.

Conversely, when the width L4 of the seating member 1400 in the second direction Y is excessively greater than the width L1 of the first storage compartment 1200 or the width L5 of the second storage compartment 1200', the volume of the seating member 1400 in the second direction Y may increase more than necessary and thus the volume of the automatic detergent dispenser 1000 in the second direction Y may increase more than necessary.

Therefore, as described above, it is appropriate that the width L4 of the seating member 1400 may have a length similar to the width L1 of the first storage compartment 1200 having a cross-sectional area S in accordance with the size of the solid detergent, in the second direction Y.

When the above-described solid detergent D is defined as a general solid detergent D that has an appropriate volume for washing in accordance with a capacity of the tub 12 of the general dishwasher 1 and has a predetermined horizontal length d1 according to the appropriate volume, a small solid detergent D' stored in the second storage compartment 1200' may be defined as a small solid detergent D' that has a smaller volume than the general solid detergent D and thus has a shorter horizontal length than the horizontal length d1 of the solid detergent D.

Further, the small solid detergent D' may be a solid detergent D' in a shape in which the general solid detergent D is partially cut in the direction of the horizontal length d1.

When a user wants to wash only a small number of dishes, it may be possible to wash the small number of dishes with a smaller detergent than the general solid detergent D that is generally used according to the capacity of the tub 12.

Apart from the general solid detergent D stored in the first storage compartment 1200, the second storage compartment 1200' may be provided to store the small solid detergent D', which is different in volume from the solid detergent D. Accordingly, a user can selectively perform the washing process using the general solid detergent D or the small solid detergent D' as needed.

A user can input information about the washing mode of the dishwasher 1 through the inputter of the dishwasher 1 or a mobile device to allow the dishwasher 1 to selectively perform one of a normal washing mode and a small amount washing mode.

The control device 1900 may control the automatic detergent dispenser 1000 to drive the first ejector 1300 or the second ejector 1300' based on a user input obtained from the main control device.

When a user selects the normal washing mode, the control device 1900 may control the automatic detergent dispenser 1000 to allow the first ejector 1300 to be driven.

When a user selects the small amount washing mode, the control device 1900 may control the automatic detergent dispenser 1000 to allow the second ejector 1300' to be driven.

Hereinafter an adjusting member 1270 configured to adjust the cross-sectional area of the storage compartment 1200 according to an embodiment will be described in detail.

FIG. 14 is a view illustrating a state in which some components of the automatic detergent dispenser of the dishwasher according to an embodiment are removed, and

FIG. 15 is a view illustrating a state in which an adjusting member of the second storage compartment is moved in FIG. 14.

For example, as shown in FIGS. 14 and 15, the storage compartment 1200 may include the adjusting member 1270 configured to adjust an internal width of the storage compartment 1200.

When the above-described solid detergent D is defined as a general solid detergent D that has an appropriate volume for washing in accordance with a capacity of the tub 12 of the general dishwasher 1 and has a predetermined horizontal length d1 according to the appropriate volume, some solid detergents D" may have a smaller volume than the general solid detergent D, and thus a width d1" of the solid detergents D" may be less than the width d1 of the general solid detergents D.

For example, when the some solid detergents D" are stacked in the storage compartment 1200 having the width L1 corresponding to the width d1 of the general solid detergent D, the some solid detergents D" may be moved in the second direction Y due to a gap between the right surface 1230 or the left surface 1240 of the storage compartment 1200 and the some solid detergents D" in the storage compartment 1200, and thus some solid detergents D" may be separated from the stacked arrangement of the solid detergents D". When the ejector 1300 is driven in a state in which the some solid detergents D" are separated, the plurality of solid detergents D" may not be moved to the third direction Y by the ejector 1300 and the some solid detergents D" may be stuck in the storage compartment 1200 and thus may not be discharged to the outside of the storage compartment 1200.

For example, the storage compartment 1200 may include the adjusting member 1270 configured to adjust the width of the storage compartment 1200 in the second direction Y, and the adjusting member 1270 may be moved in the second direction Y so as to adjust the width of the storage compartment 1200.

Even when a width d1" of some solid detergent D" is less than the width d1 of the general solid detergent D, the adjusting member 1270 may adjust a width L6 of the storage compartment 1200 to correspond to the width d1" of the some solid detergent D", and thus the stacked state of the solid detergents D" may be maintained in the storage compartment 1200.

The adjusting member 1270 may include a support wall 1271 provided to support a plurality of solid detergents and a mover 1272 connected to the support wall 1271 in the second direction Y so as to move a position of the support wall 1271 toward the second direction Y.

The adjusting member 1270 may be disposed on the right surface 1230 or the left surface 1240 of the storage compartment 1200.

When the support wall 1271 is disposed closest to the right surface 1230 or the left surface 1240, the width L1 of the storage compartment 1200 may be approximately the same as the width d1 of the general solid detergent D.

A user can adjust the width of the storage compartment 1200 by pressing the support wall 1271 toward the second direction Y. For example, a user can move the support wall 1271, which is disposed adjacent to the right surface 1230 or the left surface 1240, toward the second direction Y so as to allow the width d1" of some solid detergents D" to correspond to the width L6 of the storage compartment 1200.

For example, the mover 1272 may be extended or contracted in the second direction Y to allow the support wall 1271 to be moved in the second direction Y inside the storage compartment 1200.

For example, the mover 1272 may be provided to be movable in the second direction Y between the outside and the inside of the storage compartment 1200 to allow the support wall 1271 to be moved in the second direction Y inside the storage compartment 1200.

For example, a user can open the storage compartment cover 1140 to open the storage compartment 1200 and move the adjusting member 1270 toward the second direction Y to have a width of the storage compartment 1200 that is desired by the user. A user can selectively adjust the width of the storage compartment 1200 by gripping the support wall 1271 and moving the support wall 1271 toward the second direction Y to form the width of the storage compartment 1200 desired by the user. As a user presses the support wall 1271, the mover 1272 may be extended or contracted in the second direction Y.

For example, the adjusting member 1270 may be driven by the control of the control device 1900 by an adjusting member driver. A user can input information about the width of the storage compartment 1200 to the dishwasher 1 through the inputter of the dishwasher 1 or a mobile device, and the control device 1900 may control the adjusting member 1270 to move the mover 1272 or to expand or contract the mover 1272 so as to allow the adjusting member 1270 to be moved in the second direction Y by a predetermined distance based on the user input obtained from the main control device.

The holder 1500 may be provided to move between the support wall 1271 and one surface, on which the adjusting member 1270 is not disposed, of the right surface 1230 or the left surface 1240.

For example, the guide rail 1290 provided to guide the movement of the holder 1500 may be disposed on the support wall 1271. The holder 1500 may be translated in the third direction Z by being guided by the guide rail 1290 disposed on the support wall 1271 and the guide rail disposed on one surface, on which the adjusting member 1270 is not disposed, of the right surface 1230 or the left surface 1240.

The holder 1500 may be provided in a shape that is contracted in the second direction Y when the support wall 1271 is moved in a direction away from the right surface 1230 or the left surface 1240.

The holder 1500 may be provided in a shape that is contracted or expanded in the second direction Y. For example, the holder 1500 may be provided in a telescopic shape. Accordingly, when the support wall 1271 is moved toward the center of the storage compartment 1200, the holder 1500 may be overlapped and contracted, and when the support wall 1271 is moved in the opposite direction of the center direction of the storage compartment 1200, the holder 1500 may be expanded and extended.

The adjusting member 1270 may include a first adjusting member 1270 provided inside the first storage compartment 1200 and a second adjusting member 1270' provided inside the second storage compartment 1200'.

For example, a user can adjust the width of the first storage compartment 1200 and the second storage compartment 1200' by moving the first adjusting member 1270 and the second adjusting member 1270', respectively.

For example, a user can maintain the width L1 of the first storage compartment 1200 and the second storage compartment 1200'.

ment 1200' by not moving both the first adjusting member 1270 and the second adjusting member 1270'.

For example, a user can adjust the widths of the first storage compartment 1200 and the second storage compartment 1200' by moving one of the first and second adjusting members 1270 and 1270'.

For example, the first adjusting member 1270 may be disposed on the left surface 1240 of the first storage compartment 1200. The second adjusting member 1270' may be disposed on the right surface 1230' of the second storage compartment 1200'.

Alternatively, the second adjusting member 1270' may be disposed on the left surface 1240' of the second storage compartment 1200'. The first adjusting member 1270 may be disposed on the right surface 1230 of the first storage compartment 1200.

Alternatively, the first adjusting member 1270 and the second adjusting member 1270' may be disposed on the left surface 1240 of the first storage compartment 1200 and the left surface 1240' of the second storage compartment 1200', respectively.

Alternatively, the first adjusting member 1270 and the second adjusting member 1270' may be disposed on the right surface 1230 of the first storage compartment 1200 and the right surface 1230' of the second storage compartment 1200', respectively.

Alternatively, the adjusting member 1270 may be provided in only one of the first storage compartment 1200 and the second storage compartment 1200'.

For example, as shown in FIG. 15, the adjusting member 1270 of the first storage compartment 1200 may be disposed adjacent to the left surface 1240 to allow the width L1 of the first storage compartment 1200 to correspond to the width d1 of the general solid detergent D, and the adjusting member 1270' of the second storage compartment 1200' may be moved in the second direction Y from the right surface 1230' to allow the width L6 of the second storage compartment 1200' to correspond to the width d1" of some solid detergent D".

At this time, a user can load the general solid detergent D into the first storage compartment 1200 and load some solid detergent D" into the second storage compartment 1200'.

The storage compartment 1200 may include an adjusting member detection sensor configured to detect a position of each of the support walls 1271 and 1271'. The adjusting member detection sensor may detect a position in which the support wall 1271 of the first storage compartment 1200 and the support wall 1271' of the second storage compartment 1200' are disposed, and the control device 1900 may be configured to recognize the type of solid detergent loaded in the first storage compartment 1200 and the type of the solid detergent loaded in the second storage compartment 1200' based on the detected value.

For example, the adjusting member detection sensor may measure a distance to a position of each of the support walls 1271 and 1271', or detect a distance to a position of each of the support walls 1271 and 1271' by detecting a distance in which each of the movers 1272 and 1272' is moved, extended or contracted.

A user can input information about the washing mode of the dishwasher 1 through the inputter of the dishwasher 1 or a mobile device to allow the dishwasher 1 to selectively perform one of the normal washing mode and the small amount washing mode.

The control device 1900 may control the automatic detergent dispenser 1000 to allow the first ejector 1300 or the second ejector 1300' to be driven based on the user input

obtained from the main control device, and a value sensed by the adjusting member detection sensor.

For example, when a user selects the normal washing mode, the control device 1900 may control the automatic detergent dispenser 1000 to allow the first ejector 1300 to be driven. When a user selects the small amount washing mode, the controller 1900 may control the automatic detergent dispenser 1000 to allow the second ejector 1300' to be driven.

10 Hereinafter a process of controlling the automatic detergent input of the dishwasher will be described in detail.

FIG. 16 is a control diagram of the dishwasher according to an embodiment.

As described above, the dishwasher 1 may include the main body 10, the tub 12 provided inside the main body 10, the door 20 configured to open and close the tub 12, and the automatic detergent dispenser 1000 configured to input a solid detergent to the inside of the tub 12.

In addition, the dishwasher 1 may further include an input device 80 arranged outside the main body 10 and configured to receive an input from a user and a controller 1600 configured to control the dishwasher 1 according to the input received by the input device 80.

The input device 80 may be integrally provided with a display 81 to be described later to realize a touch screen, or may be provided in the form of a button, a touch pad, or a jog shuttle. The input device 80 may receive inputs of various operations related to the dish washing from a user.

The controller 1600 may include at least one memory 1602 configured to store a program for performing an operation described later and at least one processor 1601 configured to execute the stored program.

Meanwhile, the dishwasher 1 may further include a storage compartment sensor 1270 provided in the storage compartment 1200 to detect the inside of the storage compartment 1200. However, because the embodiment of the dishwasher 1 does not necessarily include the storage compartment sensor 1270, it is possible to exclude the storage compartment sensor 1270 according to the implementation.

40 The memory 1602 may store programs for controlling various components of the dishwasher 1 including the ejector 1300.

The memory 1602 may include volatile memory such as Static Random Access Memory (S-RAM) and Dynamic Random Access Memory (D-RAM) for temporarily storing data. In addition, the memory 1602 may include a non-volatile memory such as a read only memory (ROM), an erasable programmable read only memory (EPROM), and an electrically erasable programmable read only memory (EEPROM) for long-term storage of data.

The processor 1601 may include various logic circuits and arithmetic circuits. The processor 1601 may process data according to programs provided from the memory 1602, and generate control signals according to a result of processing.

55 The at least one processor 1601 may control the ejector 1300 to discharge one solid detergent from the storage compartment 1200 when selection of a washing course is input through the input device 80.

Particularly, when a user puts dishes into the dishwasher 1 to wash dishes, closes the door 20, and selects a washing course, the processor 1601 may control the ejector 1300 to discharge one solid detergent from the storage compartment 1200.

As described above, the ejector 1300 may include the cam member 1310 configured to move one solid detergent to the outside of the storage compartment 1200 through the rotation of the cam member 1310. The at least one processor

1601 may control the ejector 1300 to rotate the cam member 1310 to allow the solid detergent to be discharged from the storage compartment 1200.

As shown in FIG. 9, as the cam member 1310 is rotated, one solid detergent may be moved out of the storage compartment 1200, and finally, as shown in FIG. 10, the solid detergent may be seated on the seating member 1400.

The seating member 1400 may be a place where one solid detergent discharged from the storage compartment 1200 is seated, and the solid detergent moved from the storage compartment 1200 according to the rotation of the cam member 1310 may be seated on the seating member 1400.

The seating member sensor 1440 may detect an object on the seating member 1400. Accordingly, the at least one processor 1601 may determine whether the solid detergent is seated on the seating member 1400 based on the output of the seating member sensor 1440 as shown in FIG. 10.

FIG. 17 is a view illustrating a state in which a solid detergent is not present in the storage compartment.

The at least one processor 1601 may rotate the cam member 1310 one more time when it is determined that the solid detergent is not seated on the seating member 1400 after the rotation of the cam member 1310.

Even when the cam member 1310 is rotated, the solid detergent may not be seated on the seating member 1400 because an error occurs in the process of discharging the solid detergent from the storage compartment 1200. Therefore, after rotating the cam member 1310 once, the at least one processor 1601 may determine again whether the solid detergent is seated based on the output of the seating member sensor 1440. Accordingly, when it is determined that the solid detergent is not seated on the seating member 1400, the at least one processor 1601 may allow a solid detergent to be discharged from the storage compartment 1200 by rotating the cam member 1310 one more time.

When it is determined that the solid detergent is not seated on the seating member 1400 based on the output of the seating member sensor 1440 even after the cam member 1310 is rotated one more time, the at least one processor 1601 may determine that there is no solid detergent in the storage compartment 1200.

When an additional sensor is not provided in the storage compartment 1200, the at least one processor 1601 may determine the presence or absence of solid detergent in the storage compartment 1200 by controlling the rotation of the cam member 1310.

When the storage compartment sensor 1270 configured to detect the inside of the storage compartment 1200 is further included, the at least one processor 1601 may determine the presence or absence of solid detergent in the storage compartment 1200 based on the output of the storage compartment sensor 1270.

The storage compartment sensor 1270 may be a sensor configured to recognize the presence or absence of an object in the storage compartment 1200, and may employ at least one of various types of sensors such as an optical sensor, an ultrasonic sensor, an infrared sensor, or an image sensor.

The at least one processor 1601 may generate a control signal to provide a notification when it is determined that the solid detergent is not present in the storage compartment 1200 based on the above-process.

The dishwasher 1 may further include the display 81 and a speaker 82, and provide a visual notification through the display 81 or an audible notification through the speaker 82.

FIG. 18 is a view illustrating a state in which the solid detergent is discharged from the automatic detergent dispenser according to an embodiment.

The automatic detergent dispenser 1000 may further include the seating member door 1410 provided to input the solid detergent seated on the seating member 1400 into the tub 12.

5 The at least one processor 1601 may input the solid detergent into the tub 12 by opening the seating member door 1410.

Particularly, washing of dishes may be performed through a process of the pre-washing operation, the main washing 10 operation, the rinsing operation, and the drying operation. The at least one processor 1601 may open the seating member door 1410 and input a solid detergent to the tub 12 when the main washing operation starts.

The seating member door 1410 may serve to separate the 15 automatic detergent dispenser 1000 and the tub 12. When the seating member door 1410 is opened, hot and humid air in the tub 12 may flow into the automatic detergent dispenser 1000 and damage may occur to the solid detergent stored in the storage compartment 1200.

20 Accordingly, it is required to minimize a period of time in which the seating member door 1410 is opened. Accordingly, the at least one processor 1601 may control the seating member door 1410 to be closed when a predetermined period of time elapses after opening the seating member door 1410.

The predetermined period of time may mean a minimum time in which the solid detergent is stably input into the tub 12, and may be determined based on experiments, statistics, simulations, or theories.

30 FIG. 19 is a view illustrating a state in which an error in discharging a solid detergent occurs.

In the process of discharging the solid detergent from the storage compartment 1200 by rotating the cam member 1310, an error in discharging the solid detergent may occur, 35 such as the solid detergent being stuck in the intermediate door 1250 or the like.

When a solid detergent is stuck in the intermediate door 1250, a difference in power consumption or rotational speed of the motor configured to drive the ejector 1300 may occur in comparison with the normal operation. Accordingly, the at least one processor 1601 may determine whether an error in discharging the solid detergent, such as the solid detergent being stuck, occurs based on the power consumption or the rotational speed of the motor inside the ejector 1300.

45 When the storage compartment sensor 1270 configured to detect the inside of the storage compartment 1200 is further provided, the at least one processor 1601 may determine an error in discharging the solid detergent based on the output of the storage compartment sensor 1270.

Particularly, the at least one processor 1601 may determine that an error in discharging the solid detergent occurs when it is determined that the solid detergent is not seated on the seating member 1400 based on the detection result of the seating member sensor 1440 after the rotation of the cam member 1310, and when it is determined that a solid detergent is present in the storage compartment 1200 based on the output of the storage compartment sensor 1270.

When the cam member 1310 is rotated once, the solid detergent may be discharged from the storage compartment 1200 and detected on the seating member 1400 in the normal operation. However, a solid detergent may be not detected on the seating member 1400 because the solid detergent is stuck.

When a solid detergent is not present in the storage compartment 1200, the solid detergent may be not detected on the seating member 1400. Accordingly, when it is determined that solid detergent is present in the storage compartment 65

ment **1200** based on the output of the storage compartment sensor **1270**, the at least one processor **1601** may determine that an error in discharging the solid detergent occurs.

That is, when the solid detergent is not seated on the seating member **1400** although the cam is rotated once and the solid detergent is present in the storage compartment **1200**, the at least one processor **1601** may determine that an error in discharging the solid detergent, such as the solid detergent being stuck, occurs.

In this case, the at least one processor **1601** may control the cam member **1310** to rotate in a reverse direction.

The cam member **1310** may include a cam member **1310** sensor configured to detect an initial position and a rotation angle of the cam member **1310**.

When an error in discharging a detergent occurs, the at least one processor **1601** may rotate the cam member **1310** in the reverse direction to allow the cam member **1310** to be positioned at an initial position based on the cam member **1310** sensor.

Accordingly, the solid detergent that is stuck may be adjusted to be positioned in a normal position.

FIG. 20 is a control diagram of the dishwasher according to an embodiment.

As described above, the storage compartment may include the first storage compartment **1200** and the second storage compartment **1200'**.

The ejector may include the first ejector **1300** configured to discharge one of the plurality of solid detergents stacked in the first storage compartment **1200** to the seating member **1400**, and the second ejector **1300'** configured to discharge one of the plurality of solid detergents stacked in the second storage compartment **1200'** to the seating member **1400**. The first ejector **1300** may include the first cam member **1310**, and the second ejector **1300'** may include the second cam member **1310'**.

The at least one processor **1601** may first allow one solid detergent to be discharged from the first storage compartment **1200**. That is, the at least one processor **1601** may rotate the first cam member **1310** one time in a forward direction to allow one solid detergent to be discharged from the first storage compartment **1200**.

The at least one processor **1601** may determine whether a solid detergent is seated on the seating member **1400** based on the output of the seating member sensor **1440** arranged in the seating member **1400**, and when it is determined that the solid detergent is not seated on the seating member **1400**, the at least one processor **1601** may rotate the first cam member **1310** one more time in the forward direction.

When it is determined that the solid detergent is not seated on the seating member **1400** after rotating the first cam member **1310** one more time in the forward direction, the at least one processor **1601** may determine that the solid detergent is not present in the first storage compartment **1200**.

Thereafter, the at least one processor **1601** may rotate the second cam member **1310'** one time in the forward direction to discharge the solid detergent in the second storage compartment **1200'**.

When it is determined that the solid detergent is not seated on the seating member **1400** after rotating the second cam member **1310'**, the at least one processor **1601** may rotate the second cam member **1310'** one more time in the forward direction.

When it is determined that the solid detergent is not seated on the seating member **1400** after rotating the second cam member **1310'** one more time in the forward direction, the at

least one processor **1601** may determine that the solid detergent is not present in the second storage compartment **1200'**.

At this time, the at least one processor **1601** may generate a control signal for providing a notification that there is no solid detergent in the storage compartment.

In this case, the notification may be visually provided through the display or aurally provided through the speaker.

Hereinafter a case in which a solid detergent is present in the second storage compartment **1200'** will be described.

As described above, the at least one processor **1601** may rotate the first cam member in the forward direction to discharge the solid detergent in the first storage compartment **1200**. When it is determined that the solid detergent is not detected on the seating member **1400** even when the first cam member is repeatedly rotated, the at least one processor **1601** may determine that the solid is not present in the first storage compartment **1200**, and may rotate the second cam member in the forward direction to discharge the solid detergent in the second storage compartment **1200'**.

When it is determined that the solid detergent is seated on the seating member **1400** after the rotation of the second cam member **1310'**, the at least one processor **1601** may generate a control signal to proceed with the main washing operation.

In this case, a solid detergent may not be present in the first storage compartment **1200** but a solid detergent may be present in the second storage compartment **1200'**. Accordingly, for efficient operation, it is not required to rotate the first cam member of the first storage compartment **1200**, in which the solid detergent is not present, when the washing course is resumed.

Accordingly, when a selection of a new washing course is input through the input device, the at least one processor **1601** may rotate the second cam member **1310'** in the forward direction to allow one solid detergent to be discharged from the second storage compartment **1200'**.

Because the second cam member **1310'** is rotated without the rotation of the first cam member **1310**, it is possible to effectively discharge the solid detergent.

As described above, the horizontal lengths of the first storage compartment **1200** and the second storage compartment **1200'** may be formed differently or provided to be adjustable. Hereinafter an operation in this case will be described in detail.

As illustrated in FIG. 13, the horizontal length **L5** of the second storage compartment **1200** may be less than the horizontal length **L1** of the first storage compartment **1200**.

Accordingly, apart from the general solid detergent stored in the first storage compartment **1200**, the second storage compartment **1200'** may be provided to store small solid detergents having a different volume from the solid detergent, and thus a user can selectively perform the washing using a general solid detergent or perform the washing using a small solid detergent as needed.

A user can select a first mode or a second mode among the washing courses. The first mode may refer to a mode requiring a general solid detergent, that is, a standard washing course. Further, the second mode may refer to a mode requiring a small amount of solid detergent, that is, a small amount washing course or a quick washing mode.

The at least one processor **1601** may rotate the first cam member **1310** in the forward direction to allow one solid detergent to be discharged from the first storage compartment **1200** when the selection of the first mode of the washing course is input through the input device.

That is, when the washing course such as the standard course is selected, it is required to input the general solid

detergent, and thus the at least one processor **1601** may rotate the first cam member **1310** in the forward direction to allow one solid detergent to be discharged from the first storage compartment **1200** in which the general solid detergents are stored.

The at least one processor **1601** may rotate the second cam member **1310'** in the forward direction to allow one solid detergent to be discharged from the second storage compartment **1200'** when the selection of the second mode of the washing course is input through the input device.

That is, when the washing course such as the small amount washing course is selected, it is required to input a solid detergent smaller than the general solid detergent, and thus the at least one processor **1601** may rotate the second cam member **1310'** in the forward direction to allow one solid detergent to be discharged from the second storage compartment **1200'** in which the small solid detergents are stored.

It is possible to input a solid detergent that has a suitable size for the washing mode, and thus it is possible to prevent waste of detergent and to efficiently perform the washing.

In addition, there may be a case in which additional input of solid detergent is required for reasons, such as a very large number of dishes for washing, while the washing course is in progress according to the first mode.

At this time, in order to prevent over-input of solid detergent, it is possible to discharge the small solid detergent stored in the second storage compartment **1200'**.

That is, when it is determined that additional input of solid detergent is required during the first mode, the at least one processor **1601** may rotate the second cam member **1310'** one time in the forward direction to allow one solid detergent to be discharged from the second storage compartment **1200'**.

In addition, when the first mode is selected, it is required for the first storage compartment **1200** to discharge a solid detergent. However, there may be a case in which a solid detergent is not present in the first storage compartment **1200**. In this case, it is required to control the solid detergent to be discharged from the second storage compartment **1200'**.

That is, when it is determined that the solid detergent is not seated on the seating member **1400** after the first cam member **1310** is rotated once in the forward direction based on the first mode selected by a user, the at least one processor **1601** may rotate the first cam member **1310** one more time in the forward direction.

When it is determined that the solid detergent is not seated on the seating member **1400** after rotating the first cam member **1310** one more time in the forward direction, the at least one processor **1601** may determine that the solid detergent is not present in the first storage compartment **1200** and may rotate the second cam member **1310'** one time in the forward direction to allow the solid detergent to be discharged from the second storage compartment **1200'**.

When it is determined that the solid detergent is not seated on the seating member **1400** after rotating the second cam member **1310'**, the at least one processor **1601** may rotate the second cam member **1310'** one more time in the forward direction.

FIG. 21 is a control diagram of the dishwasher according to an embodiment.

As described above, the automatic detergent dispenser **1000** may further include the adjusting member **1270** provided to adjust the horizontal length of the inside of the storage compartment.

Particularly, the automatic detergent dispenser **1000** may further include the first adjusting member **1270** provided to adjust the horizontal length of the first storage compartment **1200** and the second adjusting member **1270'** provided to adjust the horizontal length of the second storage compartment **1200'**.

A user can input information about the horizontal length of the storage compartment through the input device.

That is, information about a horizontal length of at least 10 one of the first storage compartment **1200** and the second storage compartment **1200'** may be input through the input device, and the at least one processor **1601** may control the first adjusting member **1270** or the second adjusting member **1270'** to have a horizontal length corresponding to the 15 information the horizontal length.

For example, when a user inputs a horizontal length of the second storage compartment **1200'** through the input device to be shorter than the existing horizontal length, the at least one processor **1601** may control the second adjusting member **1270'** to allow the second storage compartment **1200'** to have a horizontal length corresponding to the input information.

Accordingly, as described above, small solid detergents may be stored in the second storage compartment **1200'** to 20 allow different sizes of solid detergents to be input according to the washing modes.

FIGS. 22 and 23 are flowcharts of a control method of the dishwasher.

In response to the selection of the washing course being 30 input through the input device **80** (**1601**), the ejector **1300** may be controlled to discharge one solid detergent from the storage compartment **1200** (**1603**).

Particularly, when a user puts dishes into the dishwasher **1** for washing dishes, closes the door **20**, and selects a 35 washing course, the ejector **1300** may be controlled to discharge one solid detergent from the storage compartment **1200** for the washing (**1603**).

As described above, the ejector **1300** may include the cam member **1310** configured to move one solid detergent to the 40 outside of the storage compartment **1200** through the rotation of the cam member **1310**, and the at least one processor **1601** may control the ejector **1300** to rotate the cam member **1310** so as to allow the solid detergent to be discharged from the storage compartment **1200** (**1603**).

As the seating member sensor **1440** detects an object on the seating member **1400**, the at least one processor **1601** may determine whether the solid detergent is seated on the seating member **1400** based on the output of the seating member sensor **1440**. That is, as shown in FIG. 10, the at 45 least one processor **1601** may determine whether the solid detergent is seated on the seating member **1400**.

In response to the determination that the solid detergent is not seated on the seating member **1400** as the result of the detection of the seating member **1400** (no in **1605**), the at 55 least one processor **1601** may rotate the cam member **1310** one more time (**1615**).

An error may occur in the process of discharging the solid detergent from the storage compartment **1200**, and thus the at least one processor **1601** may rotate the cam member **1310** one more time to discharge the solid detergent from the storage compartment **1200**.

In response to the determination that the solid detergent is not seated on the seating member **1400** (no in **1617**) based on the output of the seating member sensor **1440** even after the cam member **1310** is rotated one more time, the at least one processor **1601** may determine that the solid detergent is not present in the storage compartment **1200**.

In this case, the at least one processor **1601** may generate a control signal for providing a notification that there is no solid detergent stored in the storage compartment **1200** (1619).

In response to the solid detergent being seated on the seating member **1400** (yes in **1605** or yes in **1617**), and in response to the start of the main washing operation (yes in **1607**), the at least one processor **1601** may open the seating member door **1410** so as to input the solid detergent to the tub **12** (1609).

The seating member door **1410** may serve to separate the automatic detergent dispenser **1000** and the tub **12**. When the seating member door **1410** is opened, the hot and humid air in the tub **12** may flow into the automatic detergent dispenser **1000**, and damage may occur to the solid detergent stored in the storage compartment **1200**.

Accordingly, it is required to minimize a period of time in which the seating member door **1410** is opened. In response to the expiration of a predetermine period of time after opening the seating member door **1410** (yes in **1611**), the at least one processor **1601** may control the seating member door **1410** to be closed (1613).

The predetermined period of time may mean a minimum time in which the solid detergent is stably input into the tub **12**, and may be determined based on experiments, statistics, simulations, or theories.

In the process of discharging the solid detergent from the storage compartment **1200** by rotating the cam member **1310**, an error in discharging the solid detergent may occur, such as the solid detergent being stuck or the like.

As described above, in response to the selection of the washing course being input through the input device **80** (1701), the at least one processor **1601** may control the ejector **1300** to discharge one solid detergent from the storage compartment **1200** (1703).

The at least one processor **1601** may determine that an error in discharging the solid detergent occurs (1713) in response to the determination that the solid detergent is not seated on the seating member **1400** (no in **1709**) based on the output of the seating member sensor **1440** (1705) after the rotation of the cam member **1310** and in response to the determination that the solid detergent is present in the storage compartment **1200** (yes in **1711**) based on the output of the storage compartment sensor **1270** (1711).

When the cam member **1310** is rotated once, the solid detergent may be discharged from the storage compartment **1200** and detected on the seating member **1400** in the normal operation. However, a solid detergent may be not detected on the seating member **1400** because the solid detergent is stuck.

Because a solid detergent is not present in the storage compartment **1200**, the solid detergent may be not detected on the seating member **1400**. Accordingly, when it is determined that solid detergent is present in the storage compartment **1200** based on the output of the storage compartment sensor **1270**, the at least one processor **1601** may determine that an error in discharging the solid detergent occurs.

That is, when the solid detergent is not seated in the seating member **1400** although the cam is rotated once and the solid detergent is present in the storage compartment **1200**, the at least one processor **1601** may determine that an error in discharging the solid detergent, such as the solid detergent being stuck, occurs.

In this case, the at least one processor **1601** may control the cam member **1310** to rotate in a reverse direction.

As is apparent from the above description, it is possible to increase the convenience of use by storing a plurality of

solid detergents and automatically inputting the solid detergents at a necessary time when washing is performed.

Further, it is possible to increase the convenience of use by automatically detecting the presence or absence of stored solid detergent and by automatically detecting a solid detergent being stuck, and by providing feedback thereto.

Meanwhile, the disclosed embodiments may be embodied in the form of a recording medium storing instructions executable by a computer. The instructions may be stored in the form of program code and, when executed by a processor, may generate a program module to perform the operations of the disclosed embodiments. The recording medium may be embodied as a computer-readable recording medium.

The computer-readable recording medium includes all kinds of recording media in which instructions which can be decoded by a computer are stored. For example, there may be a Read Only Memory (ROM), a Random Access Memory (RAM), a magnetic tape, a magnetic disk, a flash memory, and an optical data storage device.

Although a few embodiments of the disclosure have been shown and described, it would be appreciated by those skilled in the art that changes may be made in these embodiments without departing from the principles and spirit of the disclosure, the scope of which is defined in the claims and their equivalents.

What is claimed is:

1. A dishwasher comprising:
a tub;
a door to open and close the tub;
an input device to receive a selection of a washing course;
and
an automatic detergent dispenser including:

a storage compartment having a support surface and in which a plurality of solid detergents are stackable so that the plurality of solid detergents are loaded in a vertical direction based on the tub being closed by the door and are supported by the support surface at a lowest position in the storage compartment,
an ejector to discharge a solid detergent from the lowest position, among the plurality of solid detergents loaded in the storage compartment, the ejector including a cam member configured to rotate and press the lowest position solid detergent out of the storage compartment to discharge the solid detergent outside of the storage compartment,

a seating member on which the solid detergent that is discharged by the ejector from the storage compartment is seatable,

a detector to detect whether the solid detergent is seated on the seating member, and

a processor configured to, based on the selection of the washing course being received through the input device:

control the ejector to operate so that, based on the plurality of solid detergents being loaded in the storage compartment, the solid detergent among the plurality of solid detergents is discharged outside of the storage compartment to be seated on the seating member, and

determine whether the solid detergent is seated on the seating member based on a detection result of the detector.

2. The dishwasher of claim 1, wherein the cam member includes a pressor, the cam member configured to rotate the pressor from outside the storage compartment in a forward direction into the storage

compartment to press on the solid detergent to discharge the solid detergent outside of the storage compartment, and the processor is configured to rotate the cam member one time in the forward direction to discharge the solid detergent outside of the storage compartment. 5

3. The dishwasher of claim 2, wherein the detector includes a seating member sensor to detect an object seated on the seating member, and the processor is configured to determine whether a solid 10 detergent is seated on the seating member based on an output of the seating member sensor.

4. The dishwasher of claim 2, wherein the processor is configured to rotate the cam member a second time in the forward direction in response to determining that a solid detergent is not seated on the seating member. 15

5. The dishwasher of claim 4, wherein the processor is configured to, in response to determining that a solid detergent is not seated on the seating member after rotating the cam member the second time in the forward direction: provide a notification to a user that a solid detergent is not present in the storage compartment. 20

6. The dishwasher of claim 1, wherein the automatic detergent dispenser includes: a seating member door to open to input a solid detergent seated on the seating member into the tub, and the processor is configured to open the seating member door to input the solid detergent seated on the seating member into the tub at a stage of supplying water for a main washing operation. 25

7. The dishwasher of claim 1, wherein the detector includes a storage compartment sensor to detect a solid detergent inside of the storage compartment, and the processor is configured to determine whether a solid detergent is present in the storage compartment based on an output of the storage compartment sensor. 30

8. The dishwasher of claim 2, wherein the cam member is configured to also rotate in a reverse direction, and the processor is configured to: determine whether an error in discharging the solid detergent occurred based on a detection result of the 40 detector, and rotate the cam member in a reverse direction in response to determining that the error occurred. 45

9. The dishwasher of claim 1, wherein the ejector includes a motor configured to rotate the cam member, and the processor is configured to: determine power consumption or rotational speed of the motor, and determine whether an error in discharging the solid 50 detergent occurred based on the power consumption or the rotational speed of the motor.

10. The dishwasher of claim 1, wherein the storage compartment includes: a first storage compartment, and a second storage compartment spaced apart from the first storage compartment in a left or right direction that is perpendicular to the vertical direction, and the ejector includes: a first ejector to discharge a solid detergent, among a 55 plurality of solid detergents loaded in the first storage compartment, to the seating member, and

a second ejector to discharge a solid detergent, among a plurality of solid detergents loaded in the second storage compartment, to the seating member. 11. The dishwasher of claim 10, wherein the first ejector includes a first cam member configured to rotate in a forward direction to discharge the one solid detergent outside of the first storage compartment, and the second ejector includes a second cam member configured to rotate in the forward direction to move the solid detergent outside of the second storage compartment. 12. The dishwasher of claim 11, wherein the processor is configured to rotate the first cam member one time in the forward direction to discharge the solid detergent outside of the first storage compartment. 13. The dishwasher of claim 12, wherein the processor is configured to rotate the first cam member a second time in the forward direction in response to determining that a solid detergent is not seated on the seating member after rotating the first cam member. 14. The dishwasher of claim 13, wherein the processor is configured to, in response to determining that a solid detergent is not seated on the seating member after rotating the first cam member the second time in the forward direction: rotate the second cam member one time in the forward direction to discharge the solid detergent outside of the second storage compartment. 15. The dishwasher of claim 14, wherein the processor is configured to, in response to determining that a solid detergent is not seated on the seating member after rotating the second cam member, rotate the second cam member a second time in the forward direction. 16. The dishwasher of claim 15, wherein the processor is configured to, in response to determining that a solid detergent is not seated on the seating member after rotating the second cam member the second time in the forward direction: provide a notification to a user that a solid detergent is not present in the storage compartment. 17. The dishwasher of claim 15, wherein the processor is configured to: in response to determining that a solid detergent is seated on the seating member after rotating the second cam member, perform a main washing operation, and in response to a selection of a new washing course being received by the input device after a completion of the main washing operation, rotate the second cam member one time in the forward direction so as to discharge solid detergent from the second storage compartment. 18. The dishwasher of claim 10, wherein the processor is configured to, in response to a selection of a first mode among the washing course being received by the input device, control the first ejector to discharge the solid detergent from the first storage compartment. 19. The dishwasher of claim 18, wherein the processor is configured to, in response to a selection of a second mode among the washing course being received by the input device, control the second ejector to discharge the solid detergent from the second storage compartment.

55

20. The dishwasher of claim **18**, wherein the processor is configured to, in response to the processor determining that additional input of a solid detergent is required during the first mode, control the second ejector to discharge the solid detergent from the second storage compartment. ⁵

21. A control method of a dishwasher including a tub, a door to open and close the tub, an input device to receive a selection of a washing course, an automatic detergent dispenser including a storage compartment having a support surface and in which a plurality of solid detergents are stackable so as to be loaded in a vertical direction and supported by the support surface at a lowest position in the storage compartment based on the tub being closed by the door, an ejector to discharge a solid detergent at the lowest position among the plurality of solid detergents loaded in the storage compartment, the ejector including a cam member configured to rotate and press the lowest position solid detergent out of the storage compartment to discharge the solid detergent outside of the storage compartment, a seating member on which the solid detergent discharged from the storage compartment is seatable, and a detector to detect whether the solid detergent is seated on the seating member, the control method comprising: ¹⁰

receiving the selection of the washing course through the input device; ¹⁵

controlling the ejector to operate so that, when a plurality of solid detergents are loaded in the storage compartment, the solid detergent among the plurality of solid detergents is pressed out of the storage compartment by the cam member to discharge the solid detergent to be seated on the seating member; and ²⁰

determining whether the solid detergent is seated on the seating member based on a detection result of the detector. ²⁵

56

22. The control method of claim **21**, wherein the ejector includes a cam member configured to rotate to move the solid detergent outside of the storage compartment, and the controlling of the ejector includes rotating the cam member one time in a forward direction to discharge the solid detergent outside of the storage compartment. ⁵

23. The control method of claim **22**, further comprising: rotating the cam member a second time in response to determining that the solid detergent is not seated on the seating member. ¹⁰

24. The control method of claim **23**, further comprising: determining whether a solid detergent is seated on the seating member after rotating the cam member the second time; ¹⁵

in response to determining that a solid detergent is not seated on the seating member after rotating the cam member the second time, determining that a solid detergent is not present in the storage compartment; and ²⁰

provide a notification to a user that a solid detergent is not present in the storage compartment. ²⁵

25. The control method of claim **21**, further comprising: inputting a solid detergent seated on the seating member into the tub by opening a seating member door at a stage of supplying water for a main washing operation. ³⁰

26. The control method of claim **22**, further comprising: determining whether an error in discharging the solid detergent occurred based on the detection result of the detector. ³⁵

27. The control method of claim **26**, further comprising: rotating the cam member in a reverse direction in response to determining that the error occurred. ⁴⁰

28. The control method of claim **21**, further comprising: determining whether an error in discharging the solid detergent occurred based on power consumption or rotational speed of a motor inside the ejector configured to rotate the cam member. ⁴⁵
